UNITED STATES PATENT OFFICE

ALLEN M. ROSSMAN, OF CHICAGO, ILLINOIS, ASSIGNOR, BY MESNE ASSIGNMENTS, TO ROSSMAN, SARGENT & LUNDY PATENTS CORPORATION, OF CHICAGO, ILLINOIS, A CORPORATION OF ILLINOIS

ELECTRICAL BUS AND SWITCH STATION

Application filed March 3, 1928. Serial No. 258,893.

My invention relates to transmission and distribution of electric power, and is particularly adapted to the construction of bus and switch stations of the type disclosed and 5 claimed in my co-pending application Serial No. 70,319, filed November 20, 1925. While the invention at present finds its chief application in power transmission and distribution and at voltages of from a few kilovolts 10 to around 100 kilovolts, there is no inherent limitation which confines it to power distribution nor to any particular voltages.

When power carrying conductors of appreciable voltage are brought into proximity to 15 each other, as is necessary in a bus and switch station, there is always danger of damage or destruction due to short circuits. This condition of potential short circuits is always present in any electrical net work, but, in 20 general, where only limited amounts of power are involved, the possibilities of damage are not so great and no great amount of expenditure for insulation or other protective measures can be justified.

But where relatively great amounts of power particularly at high voltage are involved, the expenditure for protective insulation or its equivalent must necessarily be 25 larger. In fact, Kelvin's law as to copper as applied to power loss, finds a close parallel in the requirements for insulation or its equivalent protection as applied to possible material damage to the system. That is to say, expenditure for protection is justified to 30 the point where the interest on the fixed charges therefor equals the mean yearly loss due to damage or possible damage.

The particular point where the greatest concentration of electrical power occurs is 35 on the bus bars. Due to the requirements for switching connections to and from these bus bars, the resultant mechanical and electrical problems are here found in most concentrated form. The switch house or switch 40 yard is the most critical structure in the system.

The switch house or yard contains essentially the busses to which is conducted the power to be distributed. Suitable circuit 45 breakers are here provided for cutting off or

turning on power flow. All of the power is available on the busses and it is here that a short circuit must not be permitted to occur. This fact is well recognized and various systems of construction have been devised to give the feature of inherent safety which is now essential for an interconnected system of generation and distribution. 55

Heretofore there have been two general 60 systems of construction based upon essentially different conceptions of the theory of preventing the creation or development of an interphase short circuit.

The two developments comprise the 65 English armor clad type of construction and the American space isolation or segregated phase type of construction.

According to the former type of construction, i. e., the armor clad, the three busses (of 70 a three phase system, which is the usual scheme of distribution) are disposed in a rigid cast metal housing which provides three longitudinal ducts for reception of the bus bars. The housing is made substantially 75 tight externally, but the ducts generally communicate internally because of the desirability of interrupting the housing for magnetic flow or eddy current flows, and also because it is not commercially feasible to make a tight joint. These ducts are filled up with a solid 80 type of compound poured hot.

The theory is to dispose the whole works in a shell of armor so strong and rigid that 85 no reasonable mechanical force can break in and no reasonable electrical or electromagnetic force can break out. The shell is at once the armor and the frame. With this type of protection the dangerous possibilities are locked, as it were, in a safe so strong that 90 nothing can break in to release it, and so strong that nothing which might reasonably happen within could break out. This is often spoken of as the armor clad or the Reyrolle 95 system.

The second system heretofore proposed and developed in the United States, proceeds upon a theory of widely different character. The theory is to segregate or isolate all apparatus of common phase, from everything 100 of different phase by actual separation in

space so great that an interphase short circuit could not reasonably occur or develop. The conductors of different phase are not brought within dangerous proximity to each other until they have passed through safety and protective devices, i. e., on the line side of the switches or switches and reactors or the like.

The theory here is to separate the component parts, i. e., scatter the dangerous components so they cannot get together except in limited quantities. The conductors and apparatus of each phase may, if indoors, or may not, if outdoors, be separated by structural walls to prevent transfer of conducting gases or the like. This system requires considerable volume or space, since space is an essential factor of the scheme. This system is often spoken of as the isolated phase or 20 Jamieson system.

Now I have observed the essential difficulties of the two theories or systems and watched their development. The armor clad system is limited in application by the expense of 25 the especially heavy cast shell or armor, the weight, size and cost of which increases enormously with increases of voltage. The type of insulation employed, i. e., a solid compound, is unsuitable for high tension protection. It tends to break down progressively and it is not self-healing as would be a fluid. But in that system a fluid insulation is not 30 practical.

In the isolated phase system increases of 35 voltage occasion increased spacings, greater volume and more conducting metal. This is not so bad as the other system, but the live conducting parts are exposed at all times and in an outdoor station such exposure is not 40 desirable.

Bearing these things in mind, I have proceeded in another direction and on a different theory in the development of my invention.

According to my invention I provide individual insulation for the phase conductors of a switch house or switch yard. This insulation is made of high grade, for example, fibrous insulation, submerged in a light insulating oil,—the whole contained in a suitable 50 sheath.

With such high grade insulation maintained about all live parts, I am able to congregate or juxtapose the insulated phase conductors to a spacing which will preserve sufficient independence to prevent damage to one conductor or piece of apparatus from being physically or mechanically transmitted to an adjacent phase conductor or piece of apparatus. At the same time free atmosphere and ground intervenes between all 60 phase conductors of different phase.

Upon consideration of this general description, it will be seen that I distinguish my structure from the old and well known practice of open juxtaposed busses, by the fact 65

that I employ complete insulation of all live parts.

My invention distinguishes from the armored type of construction first in individual high grade insulation and, second, by the provision of suitable spacing and free interposed space and ground between the insulated and metallically sheathed conductors and apparatus.

My invention distinguishes from the isolated phase system in the great decrease in volume or space required and the complete sheathing of all live parts. My system provides a compactness wholly unapproachable by the isolated phase system.

Now I wish to point out certain practical considerations which are of the greatest importance in carrying out my invention in most desirable form.

The basic idea underlying the invention is a compact structure of conductors and apparatus constituting a switch and bus station in which the power carrying conductors are all provided with individual armor and contained self-healing insulation of high order.

Whereas, in the armored construction, the armor is made so heavy and massive that, while it serves as its own frame and the support of the conductors and connected apparatus as well, and because of such ponderous weight and size is mounted directly upon the foundation, I have conceived the desirability of raising the structure of my invention to an overhead position and thereby accomplishing a number of very desirable results. First, by placing the insulated conductors and apparatus overhead, I remove the conductors from a position where they are subject to mechanical damage by workmen, or the operations normally performed about a station of this character.

Now, having decided to elevate the conductors, I may arrange the apparatus in such position that it may be "dropped", i. e., lowered to withdraw the same from circuit without any likelihood of injury to the insulated conductors.

Such elevation of the conductors being conceived to be possible and desirable, I have thereupon been faced with the problem of a practical method of doing this. The next step in the invention simultaneously solves the mechanical difficulty of such elevated mounting and the electrical problem of individual sheath losses.

According to my invention I provide a framework preferably of structural steel to furnish an elevated support. This steel framework now not only supports the weight, but it provides rigidity of support of which I immediately take advantage, i. e., I can now reduce the sheathing to a mere shell and by suitable attachment to the frame secure at once not only the necessary support against gravitation, but also the rigidity of mounting 125

which the sheathing need not now supply. By reduction of the mass of metal in the sheathing, I immediately reduce the electrical losses to a negligible quantity and the cost of construction is cut to an amazing extent. This reduction in the cost of construction can at once be appreciated when I point out that by this apparently simple and yet very important advance I may employ simple structural shapes which are standard articles in the market easily procurable, easily fabricated and easily maintained or serviced. For example, the sheathing consists in the main of standard tubing, for example copper tubing, which is easily procurable and workable. The framework which supports the conductors and sheathing and apparatus may be fabricated of standard structural steel shapes, such as angle bars, channels, I-beams, plates and the like, suitably riveted or welded together.

The sheathed conductors are preferably mounted above or superposed upon the frame in several planes, as I shall describe later, and the switches and like apparatus parts are suspended from or mounted below the frame. This puts them in a position where they are accessible for servicing without any interference from the fixedly mounted or statically disposed conductors and without danger of damage to them. By this means I am able to provide a new form of bus and switch station suitable for indoor or outdoor use having inherent safety, flexibility of design and ease of construction and operation at a cost far below anything comparable in the prior art.

Now I wish to point out at this time that as to certain features, my invention is not to be limited to switch house or switch yard construction, but is applicable to transmission lines, to underground construction, and to any desired circuit or part of a circuit whether the same is for transmission of power or for other purposes. I believe that it is broadly new to sacrifice the strength of the sheathing to adapt it better to its function of a fluid tight container of self-healing insulating medium and provide the requisite support and mechanical rigidity by the provision of a functionally and structurally separate frame member coextensive or substantially coextensive with the sheathed conductor.

In the development of my invention I have conceived the possibility of simplifying the structure by building up the sheathing of standard units suitably designed and capable of interchange and interconnection to build up almost any size or kind of station, line or connection desirable.

Thus, for example, I provide standard lengths of sheathing tube and junction boxes for connecting the ends to adjacent lengths of sheathing tube or to apparatus.

These junction boxes now provide the novel purpose of mechanically and hydraulically connecting the tubing together and at the same time mechanically connecting the sheathing to the frame and/or to pieces of apparatus.

Another feature of novelty resides in offsetting the tubing and contained conductor to make any section available for removal or replacement or service.

A further feature of novelty resides in the provision of means for permitting expansion and contraction of the various members without adversely affecting any of the desired characteristics of the elements. This includes a novel expansion joint.

A further feature of novelty resides in the interruption of the electrical conductivity of the sheathing for the purpose of avoiding dangerous sheath voltages. This may be accompanied by cross bonding and/or transposition.

Now I am aware of oil filled cable construction wherein individual high tension A. C. conductors are housed and insulated in metal sheath (which, so far as I am aware, is lead sheathing squirted or otherwise applied tight upon the surface of the insulation), but I wish at this time to point to some essential differences. First, my sheathing is loose upon the conductor and its insulation. Next, the sheathing is of much larger relative diameter and can be made of relatively much thinner walls and further from the conductor. Next, it is preferably standard tubing removable from the insulated conductor. Next, the tubing is substantially self-supporting between junction boxes, and even with the conductor therein, is sufficiently rigid to be supported solely or substantially solely from the ends, i. e., in its connections to the junction boxes. The junction boxes are rigidly supported by a functionally separate frame which forms the backbone of the system throughout. The sheathed conductors of my invention in the preferred form are not flexible, but the sheath has provision for contraction and expansion independent of the contained conductor and of the supporting frame. Likewise, the conductor is free within limits to have its own contraction and expansion without interference from the sheathing or the frame. There are further differences which will reveal themselves to those skilled in the art.

I do not intend by the above discussion of my invention to limit the same, but intend merely to elucidate the general features of the same and to call brief attention to the background of prior art from which it has emerged. There are other more specific features and elements of novelty which will at once be apparent to those skilled in the art,

and which I shall make clear by a detailed illustration and description of a specific embodiment of my invention.

Now in order to acquaint those skilled in the art with the mode of construction and use of my invention, I shall describe in connection with the accompanying drawings a specific embodiment of the same. In the drawings:—

10 Fig. 1 is a diagram of the combination of three elements which constitutes one essential aspect of my invention;

15 Fig. 2 is a similar diagram of the novel combination of the same three elements with the introduction of the junction box and its function, showing the method of support of the sheathed conductors at the junction boxes;

20 Fig. 3 is a diagram illustrating the super-position of the sheathed conductors upon an elevated frame and the suspension of the circuit breakers below the frame. This diagram also illustrates the disposition of taps or cross conductors in a plane parallel to and above the plane of the bus conductors or vice 25 versa;

Fig. 4 is a diagram of the manner of staggering lengths of sheathed conductors for convenient assembly, servicing or disassembly;

30 Fig. 5, in two parts and on separate sheets, namely, 5A and 5B, constitutes a plan view of an embodiment of my invention;

Fig. 32 is a longitudinal vertical section through the junction boxes and expansion joint employed in the modification of Figs. 29 and 30.

115 Referring now to Fig. 1, I have shown therein, in diagrammatic form, an essential conception which is at the base of the present invention. I provide for each phase a conductor, such as 1A, 1B and 1C, selectively designated by reference numeral 1. This phase conductor may be stranded or laminated, or made up in any suitable manner, and covered with a body of insulation 2 which, in the present instance is preferably a close wrapping of a fibrous vegetable material impregnated with an insulating compound, such, for instance, as a suitable phenol condensation product. For example, the conductor 1 may be wrapped with manila rope fiber paper im-

pregnated with shellac or bakelite and thereafter baked to formed a high grade formed insulation.

5 The conductor 1 is preferably made up in standard lengths insulated at the factory, provided with suitable terminal lugs or joining means and assembled in the field.

This insulated conductor is enclosed in an outer sheath 3 of metal. The metal may be 10 non-magnetic iron or other non-magnetic metal. I have found as entirely suitable for this purpose thin copper tubing preferably drawn seamless, and preferably by said drawing rendered hard so as to have a very considerable strength. The sheathing tube 3 is 15 preferably thin walled and the conductor 1 is preferably centered in the sheathing 3, the sheathing being spaced away a considerable distance from the conductor 1 either by the 20 insulation 2 or by spools or collars or other filling means which tend to center the conductor in the sheath. This sheath is rigid enough to be self-supporting in short lengths, as will be apparent later, but it would not 25 constitute sufficient armor for the conductor to be laid directly in ducts or in the ground for a number of reasons. First, it is not intended to be bent or pulled into a duct through a manhole. It is preferably of such a character 30 that it will not stand bending, and since it does not have complete internal support from the cable insulation or the conductor 1, it would tend to distort or collapse under such treatment.

35 The sheath is spaced away from the conductor and is thin walled, and thereby a novel advantage is gained, namely, that the conductive effect of current flow through the conductor upon the tube 3 is not highly concentrated 40 in a mass of metal, eddy currents are greatly minimized, a much greater ratio of heat dissipating surface to mass is obtained, and numerous other incidental advantages are attained.

45 Since the tubing 3 is adapted to support only its own gravity load and the gravity load of the contained conductor, and is not strong enough to act as a frame because of its inherently thin and unreinforced character, 50 I have conceived the possibility of making use of this form of sheathing in conjunction with structural elements having the necessary structural strength such, for instance, as the structural steel beam 4, which, as will be 55 explained more in detail later, permits of a suitable support of the conductor, its insulation, its sheath and connected apparatus, in a novel and desirable manner.

The insulation 2 is preferably made sufficient 60 to withstand the normal voltage on the conductor 1, although this is optional. Dependence for the maintenance of insulation between the conductor 1 and the sheath 3, which is necessarily and desirably grounded, 65 is placed upon a filling of insulating oil 5.

Now it will be seen that as between the phase conductors of a run of the bus, the frame element 4 is co-extensive with the sheath conductor and supports the conductor, the insulation and its sheath. The frame is 70 easily fabricated by structural iron workers, the conductors with their insulation are manufactured under factory conditions, and the assembly of the conductor and sheath is rendered facile and ingenious as possible by proper subdivision and designing, as will be 75 more apparent later.

The inherent safety in a scheme of this character is very high. It can be seen that each of the bus conductors is completely enclosed and insulated with a very high grade of insulation with the resultant possibility of the conductor being brought very close to the frame and to adjacent phase conductors. In each case the phase conductors of opposite phases are spaced sufficiently far apart so that any accidental injury to one phase conductor, or any disturbance arising on a conductor of one phase would not be mechanically or physically transmitted to an adjacent conductor of a different phase. There is in every case free open space intervening between conductors of different phases, and also there is ground intervening 85 between them in the form of the grounded tubing 3, and yet the entire station may be disposed in the open without requiring any housing or shelter from the elements.

In Fig. 2 I have shown a further development of the elementary idea disclosed in Fig. 1. The sheathing tube 3 is now provided with flanges on its ends as indicated at 6, and the flanges are joined to suitable junction boxes, such as 7 and 8. The conductor, with its applied insulation, is now made up into unit lengths 9 provided with suitable joining lugs 10 and 11 to be inserted inside of the tube 3 with the connecting lugs 10—11 disposed within the junction boxes 7 and 8. The conductor lengths 9 are held centralized in the tubes 3 as by spools or rings of insulation 12—12, and the entire interior of the tubes 3 and junction boxes 7—8 and connected parts, is filled with the insulating oil. The joints made at the lugs 10 and 11 are suitably covered with handwrapping, as indicated at 13—14 to provide a complete insulation for the live parts independently of the body of insulating oil.

The steel frame member 4 is now connected with other suitable frame members to form a frame work 15 co-extensive with the run of the sheath conductor. In this form the weight of the sheath conductor and connecting boxes is transmitted through the junction boxes 7 to the frame. These junction boxes are preferably made of manganese steel or other non-magnetic metal or alloy having sufficient mechanical strength 125 to perform their function without interfer-

ing with the electric and magnetic duty of the conductors.

At the joint of the terminal 11 in Fig. 2, a vertical run of conductor is shown at 16 5 extending downwardly in a suitable run of the sheath 17 indicating the manner in which taps may be taken off of the main run of conductor.

In Fig. 3 I have indicated diagrammatically 10 a further elaboration of the fundamentals heretofore discussed. In this case the structural steel framework 15 is now elevated on suitable posts or pillars 18-18 to place the sheath bus conductors above the 15 said structural framework 15 where the said sheath conductor and its junction boxes are unlikely to be injured or damaged. The framework 15 is raised sufficiently overhead to permit ample clearance for workmen to 20 pass under the same and under such apparatus as is suspended from the frame 15.

The sheath conductor indicated at 23, connected between the junction boxes 19 and 20, is, in this form, adapted to be connected to 25 the sheath conductor 25 arranged in a plane above the plane of the sheath conductor 23 by means of the circuit breaker 26. The circuit breaker 26 is electrically connected by a suitable set of disconnectible couplings to 30 said conductors 23 and 25, and is mechanically suspended from the framework 15 by means of suitable mechanical connections 27-27, in the present instance indicated as suitable bolts and brackets.

35 By disposing the conductors 23 and 25 in different planes, it is now possible to provide openings in the sides of the junction boxes to permit access to the ends of the insulated conductors, as indicated by the cover 40 plate 28 in Fig. 3, which cover plate is in line with the run of the insulated conductor 23. Likewise, on the back side of the junction box 20 a removable cover plate of similar character is provided in line with the 45 conductor 25. Within the junction box 20 provision is made for joining the ends of the horizontal conductors with the vertical terminals of the circuit breaker 26, as will be described in detail later.

50 Fig. 4 now shows a further development of the idea of offsetting adjacent lengths of conductors in the same run. In the longitudinal run of conductors shown in Fig. 4 alternate lengths, such as 3-32 are arranged in 55 a plane on one level and the other lengths 31-33 are arranged at a lower level. Transverse conductors, such as indicated at 34 may be arranged at an intermediate or at a higher level if so desired, and cross-connections may 60 be made within the junction boxes.

By thus arranging alternate lengths on different levels, each standard length of conductor is thereby made accessible by removal of the cover plates such as 35-35. Obviously, 65 two adjacent lengths may be continued in

the same plane on the same level, the connections between adjacent lengths being accessible through the top of the junction boxes by removal of cover plates such as 36-36. It is to be understood, of course, that the runs 70 of conductor and the connected junction boxes are filled with insulating oil. At suitable points in the run of conductor stop joints may be interposed, in order to sectionalize the body of oil to prevent excessive leakage in 75 case of accidental rupture of the enclosing sheath. The specific manner of accomplishing this will be disclosed later.

Now by reference to Figs. 5 to 18, inclusive, in which I have indicated more or less diagrammatically a further development of the fundamental idea of my invention, I shall explain how the foregoing elementary features may be embodied in a switch and bus yard. This particular design has been laid out with 80 reference to the requirement of a specific substation, namely, the Wheaton sub-station at Wheaton, Illinois, U. S. A., in the system of the Public Service Company of Northern Illinois.

The frame structure comprises pairs of posts or pillars 40 to 48, inclusive, shown in Figs. 6A and 6B. Upon these posts there is mounted a horizontal frame generally designated by the reference numeral 49, comprising four longitudinal beams or girders 51-52-53 and 54 disposed between side sills 50 and 55 and all joined together by a series of cross beams 57 to 65, inclusive, dividing the structure into eight similar bays, as indicated in Figs. 5A and 5B.

Each of these eight bays is provided with three transverse closed troughs comprising a closed box-like structure extending transversely across the frame. These bus troughs are indicated by the reference numerals 66 to 73, inclusive, the individual troughs of each group being devoted to individual phases and indicated by the phase letters as, for example, 66A, 66B and 66C.

The main bus 75 comprising the three runs 75A, 75B and 75C extends longitudinally of the lower ends of the bus troughs as viewed in Figs. 5A and 5B, while the transfer bus 76 comprising the three runs 76A, 76B and 76C, extends longitudinally across the opposite ends of the bus troughs. These runs of bus are subdivided into standard unit lengths of sheaths and conductors between the junction boxes which are mounted in staggered relation upon the corresponding ends of the bus troughs. Thus, for example, the main bus 75 is supported on and connected through junction boxes 78, the individual boxes being indicated by the phase letters as, for example, 78A, 78B and 78C on the bus troughs 66. In like manner the main bus is supported on the successive series of bus troughs through junction boxes 79 to 85, inclusive.

In like manner the transfer bus 76 is connected through and supported upon the junction boxes 86 to 93, inclusive, on the opposite ends of the bus troughs. These junction boxes are all provided with suitable flanged necks adapted to join the flanged ends of adjacent sheathing tubes and are provided with suitable removable covers on the sides which face outwardly as indicated at 94 and 95 in Fig. 7. They are also provided with suitable flanged necks on the bottom sides for joining with suitable flanged necks extending up from the bus troughs.

To facilitate the insertion or removal of the conductor from the sheath, two adjacent lengths of sheath and conductor are arranged in alignment on one level and then two adjacent lengths are arranged in alignment on another level, either above or below. For example, in Fig. 6A, adjacent lengths 96 and 97 are arranged in alignment extending through the junction box 79C from the junction box 78C to the junction box 80C, whereas, the continuations of the same, 98 and 99, extend in alignment through the junction box 81C connecting from junction box 80C to 82C. Connection between the upper and lower levels is then made, for example, in the junction box 80C between adjacent lengths 97 and 98. By such arrangement the sheath and junction boxes may all be built up, leaving the end covered and flanged openings, which are endwise in alignment with runs of sheath, open for the insertion of the conductor lengths and the cross connection of the same.

Now the junction boxes not only serve to connect the bus longitudinally, but also permit taps to be taken down through the junction box into the corresponding bus troughs. The bus troughs may, of themselves, be made strong enough to support depending apparatus, such as the circuit breakers, current transformers, potential transformers and the like, or, if desired, additional frame members may be provided for taking the weight of such elements. As shown herein, the weight is supported either from the bus troughs directly or, in the case of oil circuit breakers and like apparatus, from longitudinal beams, such as 51, 52, 53 and 54, as shown in Figure 7.

In the layout shown in Figs. 5A, 5B and Figs. 6A and 6B, the first bay at the left of Fig. 5A is shown as devoted to the taking off of a line circuit. By reference to Figs. 7 and 13, the connections for the line circuit, which is laid out as a line leading to Aurora, Illinois, may be better understood. The connections in the three bus troughs 66A, 66B and 66C are alike, since they are simply the three phases for the given line. The line is taken off through three single phase cables 37, of which the individual single phase cable 37C is shown in

Fig. 7. This cable comes up through a protective conduit 38, which is made up of a length of duct such as employed underground coated with a wrapping of rope covered with cement and formed into a unitary or monolithic tubular duct. At the upper end of the single phase cables 37 suitable end bells 100 are connected between the sheath of the cable and the bottom of the boxes 66. A suitable hand hole and cover plate 101 is arranged over each of the potheads 100 for access to the same for inspection, installation and repairs. In the pothead 100 the conductor of the cable is joined to an insulated conductor of the type heretofore described, namely, a stranded or laminated conductor provided with a suitable wrapping of insulation adapted to be submerged in oil with which the box trough is filled. A short conductor 102 is connected to the horizontal length of conductor 103 to form a T connection. The conductor 103 extends to the right to a terminal 104 mounted in fluid tight relation in the bottom of the bus trough 66 to provide a detachable coupling contact for the potential transformer 105 for each box trough 66. The conductor 103 is then extended further to the right where it is connected to the detachable coupling contact 106 to which there is adapted to be connected one terminal of the reserve circuit breaker 107. The opposite terminal of the circuit breaker 107 is adapted to be connected to the coupling member 108 mounted in the bottom of the box trough in fluid tight relation thereto, and from the contact of the coupling 108 a conductor 109 leads up through a neck 110 which is provided with a suitable coupling flange for bolting to the flanged neck 111 on the bottom of the junction box 86. The conductor 109 leads up to the longitudinal run of conductor in the run of cable 75 which is extended through the junction box 86.

The left end of the conductor 103 extends into the double terminal coupling member 112, also secured in the bottom of the box trough, which double contact coupling is adapted to make connection with the terminals of the current transformer 113.

From the coupling member 112 a conductor 114 extends over to the coupling member 115 which is adapted to make contact with the terminal of the main oil circuit breaker 116, the opposite terminal of which is adapted to make contact with the coupling member 117. From the coupling member 117 a conductor 118 extends up through the flanged neck 119 and the corresponding flanged neck 120 of the junction box 78 to make connection with the run of conductor of the corresponding bus 75.

The coupling members heretofore described for the circuit breakers, the current transformer and the potential transformer, are connected to the bottom wall of the

trough and expose the contact members in the form of sockets so that the stud contacts of the pieces of apparatus may be withdrawn therefrom when the oil circuit breakers are 5 open to permit disconnection of the circuit breakers, current transformers, potential transformers and the like. By this arrangement no disconnect switches are required.

Suitable hand holes and cover plates are 10 provided over the coupling members of each piece of apparatus heretofore described.

Fig. 13 shows a single line diagram of connection of the section of Fig. 7. The three bus troughs 66A and 66B and 66C are alike, 15 differing only in the location of the junction boxes and the corresponding difference which is made in the lengths of the conductors 118 and 109 to bring about the connection.

It is to be noted that the corresponding 20 parts are all given corresponding reference numerals and that the letters added to the reference numerals are intended only to distinguish for the individual phases which are indicated as phases A, B and C.

25 The second bay, in Fig. 5A, represents the connections for a line running to Batavia, Illinois. These connections are identical with those in bay 1 and are shown in Figs. 7 and 13.

30 In bay 3 there are shown the connections for a bus section, that is, the circuit breakers in this case, instead of being employed for connecting a line to a bus or connecting the main bus to the transfer bus, are employed 35 to cut the main bus or connect two sections of the same.

Reference is now made to Figs. 8 and 14 in explanation of the same. It will be observed 40 from an inspection of Fig. 6 that the two adjacent lengths of sheath tubings and their contained conductors, as shown at 97 and 98, are on different levels where they enter the junction boxes 80 and 81. The bus conductor in the upper level is connected through junction

45 box 80 to a laterally extending conductor 122 which is sheathed in a tube 123 connected between the junction box 80 and another junction box 124. The junction box 124 is connected to the bus trough 68 through the

50 flanged coupling necks 125 and 126. A conductor 127 connected to the conductor 122 extends down and joins the conductor 128 in the bus trough 68. The conductor 128 at its right hand end is connected to a coupling member 129 for making connection with the potential transformer 130. At its left hand end the

55 conductor 128 is connected to the coupling member 131 which is adapted to make connection with one terminal of the oil circuit breaker 132. The opposite terminal of the oil circuit breaker 132 is adapted to be connected to the coupling member 133, and from the coupling member 133 a conductor 134

60 leads up through the flanged neck 119 and 120 from the bus trough 68 to the correspond-

ing junction box 80 where the conductor 134 is joined to the run of conductor 98 arranged at the lower level.

Now it can be seen that the extreme left hand section of the bus, including bays I and II, can be connected or disconnected through the oil circuit breakers 132.

It will be observed from the diagram of Fig. 14 that the potential transformer 130 is connected to bays I and II and when the circuit breaker 132 is opened the said potential transformer 130 is disconnected from the bus other than bays I and II.

Bay IV is devoted to a bus tie, namely, a connection between the run of bus 75 and the 80 run of transfer bus 76. In this case the bus trough 69 contains a tie conductor suitably connected through a current transformer and an oil circuit breaker to connect the main bus to the transfer bus. This connection includes 85 the conductor 135 extending from the phase conductor of the transfer bus down through the flanged joining necks between the junction boxes 89 and the corresponding bus troughs 69, connection being made at 136 to the coupling member for the potential transformer 137. The conductor 135 extends over to the double coupling member 138 for making connection with the terminals of the current transformer 139. The coupling member 95 90 95 138 is connected by a conductor 140 to the coupling member 141 for the oil circuit breaker 142, the opposite terminal of which is adapted to be connected to a coupling member 143 and it, in turn, is connected by the conductor 144 to the corresponding main bus phase conductor through the junction box 81.

It will be observed that the junction boxes 81 and 89 are single deck boxes made high enough to accommodate only the lower level 105 of the runs 98 and 99, but it will be apparent that the junction boxes might all be made double deck, although only the lower parts of some of them would be employed.

From the above description and from the 110 diagram of Fig. 15, it can be seen that the circuit breaker 142 serves to open and close a tie connection between the main bus and the transfer bus.

Bay V is connected to an incoming line 115 shown by the incoming cables 145, shown in dotted line in Fig. 5B.

Bay VI is a bay devoted to a bus section connection like the one shown in bay III and is, for all practical purposes, identical 120 therewith.

Bay VII is a bay devoted to an outgoing line, for example, to Bellwood, Illinois, and is in all essential respects like bay I. Bay VIII is another bay devoted to an outgoing line, namely, the second line to Bellwood, and is in all essential respects like bay I.

It will be observed that each of the bays is arranged to have a circuit breaker operating mechanism disposed adjacent the circuit 125 130 135 140

breakers for operating the three circuit breakers for a given connection in unison. Since this forms no part of my present invention, I have not shown the details of the operating mechanism.

Now referring to Figs. 10 and 16, I have here shown how the main features of my invention may be applied to single bus switching. If only a single bus, that is, the main bus, is to be employed, then the run of auxiliary bus 76 may be omitted. In that event the main bus is connected to the incoming and outgoing lines through a connection leading through the current transformer. For example, as shown in Fig. 10, the incoming cable 146 extends through the bell 147 into contact with a conductor 148 which leads to one contact of the double coupling member 149 connected to one side of the current transformer 155, the other contact of which is tapped through a T connection to the conductor 150, which conductor 150 extends longitudinally of the bus trough 151, the right hand end of said conductor 150 being connected to the coupling 152 of the potential transformer 153 and the left hand end of the conductor 150 being connected to the coupling member 154 of the oil circuit breaker 156. The other terminal of the oil circuit breaker 156 is adapted to be connected to a coupling member 157, and that coupling member is in turn connected to a conductor 158 to the main line bus conductor 159 extending through the junction box 160. This arrangement shows the possibility of leading a conductor in parallel with another conductor, so long as the two are of single phase, within the same bus trough.

The structure is applicable to a number of combinations of circuits, as will be explained in connection with Figs. 11, 12, 17 and 18. Referring now to Figs. 11 and 17, I show a structure in which main and transfer bus switching may be accomplished. In this case the bus conductor 161 is connected by a conductor 163 extending down through the bottom of the junction box 162 to one coupling 164 of the oil circuit breaker 165, the other terminal of the oil circuit breaker being adapted to be connected to the coupling 166 which is connected by a conductor 167 to one terminal of the double coupling member 168 for the current transformer 169, and is further connected to the coupling member 170 of the potential transformer 171 and then extends over to the coupling member 172 of the transfer circuit breaker 173, the other terminal of which is adapted to be connected to the coupling 174 and it, in turn, is connected by conductor 175 to the bus conductor 176 of the transfer bus.

The line or feeder connection comes in through cable 177, pot head 178, and joins the conductor 179 which is extended to one

of the contacts of the double coupling member 168.

Now it can be seen that so long as the reserve or transfer circuit breaker 173 is removed from engagement with the coupling contact 172 and 174, the line or feeder 177 is connected through the current transformer 169 and the main oil circuit breaker 165 to the main bus 161. By inserting the reserve or transfer circuit breaker 173 in place, current may be fed from the bus 76 to the line 177, the circuit breaker 165 being then open, and it may at this time be disconnected. If both circuit breakers are closed current may be fed to the line 177 or received therefrom by both main and transfer busses.

The line may be disconnected by breaking the current flow through the connected circuit breakers and by thereafter disconnecting the current transformer 169 at the coupling 168.

Where the line is to be connected to both main and transfer busses 161 and 76, the oil circuit breaker 173 may be maintained in contact and the two circuit breakers operated in unison to disconnect the line 177. This arrangement is shown in Figs. 12 and 18.

Referring now to Figs. 19 to 24 inclusive, I shall describe the embodiment of my invention, which is now being erected at Wheaton, Ill., U. S. A. Referring first to Fig. 22, in which I have shown a line diagram of my invention in single line form, the main 33 kv. bus 180 is arranged to feed a series of lines, in this case six lines numbered 181, 182, 183, 184, 185 and 186 respectively. One of these lines, for example, line 186, may be the incoming power line, and the other lines are outgoing lines. The line 186 includes the reactor 187, current transformer 188, and then leads by branch 189 through the circuit breaker 190 to the main bus 180. Another branch 191 extends over to make connection with the reserve bus 192, which parallels the main bus 180. The connections made through oil circuit breaker 193, which at each side thereof is provided with disconnectible contacts 194', 195', as will be explained further in detail. Likewise the main oil circuit breaker 190 is provided with disconnectible terminals 194, 195 of like character.

Where only a small amount of power is involved the reactor such as 187 may be dispensed with. The station is divided into seven bays, the first six of which are devoted to incoming and outgoing lines, and the seventh being devoted to low voltage transformation and switching for providing operating current and control current in the station. The first six bays are substantially identical in electrical connections, and hence the description of the sixth will suffice for an understanding of the others. An instrument transformer 196 is connected through a fuse 197, current limiting resistance 198

- and disconnectible contacts 199 to the branch conductor 191. By this connection the potential on the line 186 is ascertainable whether the line be connected through the 5 main circuit breaker 190 to the main bus 180, or through the oil circuit breaker 193 to the reserve bus 192. The low voltage bay, indicated as bay 7 in Fig. 22 and appearing in plan view in Fig. 19G and in side elevation 10 in Fig. 20G, includes a suitable transformer 200 for transforming current from 32 kv. to a suitable operating voltage led off by way of the line 201. The transformer 200 is in series with the fuse 202, current limiting resistance 203, and disconnectible contacts 204, all connected in series to the main bus 180. A like set of apparatus is connected to the reserve bus 192, and is indicated by like reference numerals primed. 15
- 20 Referring now to Figs. 19 and 20, the station includes the structural frame consisting of longitudinally extending sills 205 and 206, which preferably consist of I-beams, as may be seen on Figs. 21A and 21C. These longitudinal sills are connected to a series of posts or columns which support the sills at a suitable distance overhead. The columns under the sill 205 are numbered 207, 208, 209, 210, 211, 212, 213 and 214. The columns under the 25 sill 206 supporting the same are numbered 215, 216, 217, 218, 219, 220, 221 and 222. These posts are supported on suitable foundations of concrete or the like. The posts are connected together in pairs by cross beams numbered 223, 224, 225, 226, 227, 228, 229 and 230. These cross beams 223 to 230 inclusive divide the structure into bays, such as indicated on Fig. 22, namely bays I to VII inclusive. Between adjacent cross beams, such as 223 and 224 in bay I (see Fig. 19A), I provide a supporting structure for the oil circuit breakers, such as 231 and 232 shown in cross sectional view in Figs. 21A, B and C. The oil circuit breakers are arranged in 40 groups of three for three-phase service, each such group of three being connected together by suitable framework so that they may be handled as units, that is, as a group instead of as individual phase devices. These groups are operated in unison by common breaker mechanism, which is not shown for the sake of clearness and as the same forms no part of my invention. The circuit breakers, as shown more in detail in Fig. 23B and as 45 shown in dotted lines in Figs. 21D and 21E, have quick, detachable terminals 233, 234 mounted on the upper ends of the insulating bushings 235 and 236, adapted to enter stationary spring terminals such as 237, 238 shown in Fig. 23B. The terminals on the 50 circuit breakers are releasable from the stationary terminals by lowering the circuit breakers, whereupon the terminals are separated. Due to this mode of connection disconnect switches are not employed in this 55

specific embodiment, although it is apparent that disconnect switches might be employed, being treated in that case as a piece of apparatus mounted upon a framework and connected in its proper relation to the corresponding circuit breaker by the armored oil-containing sheathing which is employed for power carrying conductors throughout. In each bay an intermediate framework for supporting the circuit breakers and junction boxes is employed. I shall describe this in connection with Fig. 19B and Figs. 21A, 21B and 21C. This intermediate framework is connected between the cross beams 224 and 225, and it comprises fabricated channel beams of a deep section equal in depth to the side sills such as 205 and 206 and connected between the transverse beams 224, 225, which are of similar fabricated channel construction or I-beam construction. Thus to provide a mounting for the circuit breakers 231 and 232 I employ fabricated beams 240 and 241 lying on opposite sides of the circuit breakers 231 and extending longitudinally of the station between the cross beams 234 and 235. Then to provide mounting for circuit breakers 232 I employ similar fabricated beams 242 and 243 likewise extending between the cross beams 224 and 225 and running longitudinally of the station. A sheet metal plate or platform 244 is laid upon beams 240 and 241 and firmly secured thereto as by riveting, bolting or the like, and this platform provides a mounting for the terminals such as 237, 238 shown in Fig. 23B for the terminals 100 of the circuit breaker 232. To this end box-like housings 246A, 246B and 246C are provided to support the contacts for one side of the circuit breaker group 231. In like manner box-like housings 247A, 247B and 247C 105 are mounted on the plate 244 to support stationary detachable terminals like the terminals 238 for the other side of the circuit breaker group 232. It will be observed that the housings 247A, 247B and 247C have extensions to the right, as viewed in Fig. 19B, for making connection with the cross-wise extending sheaths and housing conductors corresponding to conductors 191 of Fig. 22. In like manner the box-like housings 248A, 248B and 248C are mounted on the platform 245 to house one group of terminals for the circuit breaker group 232 and another set of box-like housings 249A, 249B and 249C house the other terminals of the circuit breaker group 232, and extensions on the right hand side of the same provide connection with the sheathing for containing another pair of conductors corresponding to conductor 191 of Fig. 22. 110

The frame for the bay under discussion, namely, bay II shown in Figs. 19B and 20B, includes a series of relatively short bars or beams 250A, 250B and 250C, connected between side sill 205 and the longitudinally ex- 115 120 125 130

tending beam 240, which supports one part of the platform 244. These short beams 250A, 250B and 250C support junction boxes 251A, 251B and 251C, which are in series with the main bus. In a like manner short bars or beams 252A, 252B and 252C are connected between the door of side sill 206 shown in Fig. 19B and the longitudinally extending beam 243, which serves to support one end of the platform 245. Junction boxes 253A, 253B and 253C are mounted on the beams 252A, 252B and 252C, these junction boxes being contained in the longitudinal run of the reserve bus. The framework further contemplates laterally extending cantilever beams 254A, 254B and 254C extending outwardly in pairs from the side sill 205 to support housings 255A, 255B and 255C containing current transformers like the current transformer 188 shown in Fig. 22.

On the opposite side, that is, on the side of the reserve bus 192, a platform 256 is supported on cantilever beams, such as 257, shown in Fig. 21C, for supporting housings 287A, 287B and 287C, which are disconnecting device junction boxes for housing the stationary disconnecting contacts for potential transformers such as 196 in Fig. 22, current limiting resistance 198 and high tension potential transformer fuses 199. Adjacent housings 258A, 258B and 258C constitute disconnecting device junction boxes for the disconnecting contacts for the opposite side of the potential transformers and protective devices unit. The unit itself is indicated at 259 in Fig. 21C and it comprises an oil filled casing containing three such instrument potential transformer 196 connected between phases for the purpose of giving an indication of voltage on voltmeters, wattmeters and the like. The disconnecting contacts 260 in the housings 258A, 258B and 258C are connected together to form a star connection by means of conductors housed in the short sheath sections 261 shown on Fig. 19B.

The frame member of the station further comprehends two longitudinal overhead tracks 262 and 263, which are formed in the shape of suspended I-beams provided with suitable waterproof housings 264 and 265, the beams 262 and 263 being suspended from longitudinally extending sills in the form of I-beams 266 and 267 shown in Figs. 21A and 21C, and running the full length of the station through all of the bays. These I-beams 266 and 267 are not continuous through the cross beams such as 223, 224, 225 and the like, but are formed as sections between such cross beams, being firmly secured thereto and constituting further bracing, but the tracks 262 and 263 are continuous throughout the station for the purpose of supporting a suspended U-shaped elevator frame, the vertical portions of which are indicated at 268 and 269 in Figs. 21A, 21C, 21D and

21F and the horizontal platform thereof at 270 (see Fig. 21F). This horizontal platform carries a pair of cross rails 271 on which an elevator car 272 is adapted to travel.

Obviously in my invention the platform 270 may be mounted upon the foundation instead of being suspended upon the frame. That is to say, the tracks 262 and 263 may suitably be placed at the base of the posts or columns instead of at the heads of the same.

The elevator car 272 has a suitable, vertical movable carriage 274, which is adapted to receive a circuit breaker unit such as the unit 231 or the unit 232 in any one of the bays, and to lower the same or to raise the same. In Fig. 21 I have shown the elevator carriage 274 as lowered to its bottom position and the car 272 upon which the elevator is mounted moved to the central position where it clears the circuit breakers so that the circuit breaker unit shown in dotted lines in Figs. 21B and 21E may be transported longitudinally of the station. The elevator is provided with suitable electric operating mechanism under the control of suitable controller mechanism indicated at 275.

The station further comprehends a pair of outside suspended trackways, one of which is shown at 276 in Fig. 21C. This trackway is adapted to extend the full length of the station, being suspended on the cantilever beams 257 and covered with weather hood 277. A traveling frame 278 is suspended on suitable rollers bearing on the flanges of the I-beams 276, this frame providing a vertical trackway for a movable elevator platform 279, which in the present instance is adapted to be operated manually as by means of the crank 280 shown in Fig. 21F.

The lower end of this traveling frame 278 (see Fig. 21C) bears laterally against a longitudinally extending trackway 281 (see Fig. 21F) supported by the posts on the side, a plurality of rollers 282 being mounted on the traveling frame and tracking upon the longitudinal track 281. The platform 279 is adapted to be raised to receive a potential transformer unit such as 259 shown in Fig. 21C and to lower the same in order to disconnect them from their releasable terminals such as 260 and 283 in the housings 258 and 287 respectively. In this manner any one of the potential transformer units may be supported on the elevator platform 279, mechanically unlocked and lowered to disconnect them and disengage them from their stationary contacts and then transported longitudinally of the station. Upon the opposite side of the station and extending only along the seventh bay shown in Figs. 19G and 20G a similar traveling frame 284 with suitable elevator platform 285 is provided. The purpose of this frame and elevator is to

serve the potential transformer unit 286 shown in Fig. 19G and Fig. 21A.

I shall now refer to the electrical characteristics of this station. The main bus indicated generally at 180 (see Fig. 19B and Fig. 19A) comprises the longitudinal run of sheathed conductors indicated separately as 180A, 180B and 180C. While these sheathed conductors are electrically continuous throughout the length of the station, they are mechanically interrupted for greater ease in assembly, service and repair. Likewise the reserve bus 192 comprises the longitudinal run of three sheathed conductors 192A, 192B and 192C likewise electrically continuous, but mechanically discontinuous for the same purpose. Beginning with bay I, Fig. 19A, I provide the three junction boxes 288A, 288B and 288C connected to the left hand end of the main bus 180. These junction boxes are of a height great enough to accommodate a connection to only one sheath, whereas by reference to Fig. 19B and Fig. 20B, it will be seen that the junction boxes 251A, 251B and 251C have two sheath connections. The run of sheath 289A connects the junction box 288A to the junction box 251A at the lower level of said junction box 251A. An expansion joint 290A is connected in said sheath 289A. In like manner the sheath 289B extends from the junction box 288B to the lower part of the junction box 251B and in like manner the sheath 289C extends to the lower part of the junction box 251C. These sheaths 289B and 289C also include expansion joints 290B and 290C. The structure of the expansion joints is shown in detail in Fig. 25. Within the junction boxes 251A, 251B and 251C the corresponding conductors in the sheaths 289A, 289B and 289C are joined to the conductors which are contained within the sheaths 291A, 291B and 291C which connect the upper part of said junction boxes 251A, 251B and 251C with the upper parts of corresponding junction boxes 292A, 292B and 292C. It will be observed that there is a lateral connection from the junction boxes 251A, 251B and 251C extending to the disconnecting device junction boxes 246A, 246B and 246C through the short runs of sheathing and conductor indicated at 293A, 293B and 293C. These high junction boxes 251A, 251B and 251C thus provide for connection of the sheathing at the lower level on one side, at the upper level on the opposite side, and the intermediate connection 293A, 293B and 293C at the intermediate level. Now by reference to Figs. 19B and 28 it will be observed that the conductor such as 294 shown in Fig. 28 enters at the top level and makes connection through a flexible conductor 295 to a central connecting block 296. In a like manner the lower conductor 297 makes connection through the flexible conductor 298 to the central block 296, as by means of suitable bolts

and clamps, so that the conductors 294 and 297 have a releasable connection with the flexible conductors, and the flexible conductors in turn have a releasable connection with the central connecting block 296. The central connecting block 296 in turn is connected with the laterally extending conductor 299 so that a three-way connection is made in a junction box of this type. The junction boxes 292A, 292B and 292C are of the low type, but are mounted at a level above the junction boxes 288A, 288B and 288C by the use of longer pedestals such as 300 shown in Fig. 20C.

From the opposite sides of junction boxes 292A, 292B and 292C the bus 180 extends in the sheaths 301A, 301B and 301C to high type junction boxes 302A, 302B and 302C. Here by the same type of three-way connection in the high junction boxes 302 the bus continues through the low type junction boxes 304A, 304B and 304C to another set of high type junction boxes 306A, 306B and 306C. From thence at a higher level and through the sheaths 307A, 307B and 307C the bus extends on to the final low type but elevated junction boxes 308A, 308B and 308C. It will be observed from Fig. 19 that each length of sheath contains an expansion joint of the type shown in Fig. 25. In the low type of junction box the three-way connection is made as shown in Fig. 20E. In that construction the end of the incoming conductors indicated at 309 and 310 are connected to flexible leads 311 and 312 respectively, and they in turn are connected to a connecting block 313 to which the laterally extending conductor 314 is in turn connected.

The reserve bus is constructed and connected throughout the respective bays in the same manner as has been described in connection with the main bus 180. It is thought, therefore, that it will not be necessary to describe these connections in detail. However, as will be observed from Fig. 19, the current transformers are all placed on the side, appearing at the top of Fig. 19, whereas the potential transformers and their protective apparatus appears on the side of the station shown at the bottom of Fig. 19.

Referring now particularly to line 182, see Figs. 22, 19B, 20B and 21, the incoming line arrives at the station either overhead or through an underground cable, and where reactors such as 187 are employed, they are preferably disposed on foundations along the sides of the station. From the inner terminals of the reactance coils 187 a single phase cable is led upward under the current transformer box 255C, as shown in Fig. 21A, where the lead sheath 315 is connected through an end bell 316 to a flanged neck 317 on the bottom of the junction box 255C. The conductor in the cable indicated at 318 is connected through a suitable detachable coupling 319

to the shunt conductor 320, the other end of which is connected through a coupling 321 to a transversely extending conductor 191. A current transformer 188 is connected in parallel with the shunt conductor 320, and is suitably mechanically supported within the junction box 255C. This conductor 191 then extends through a flanged neck 323, then through the connected expansion joint 324, then through the sheath 325 over to the lateral extension 326C of the disconnecting device junction box 247C wherein the joint 327 is made. At this joint 327 a lateral connection leads to the disconnecting contact contained within the housing or junction box 247C, which connection corresponds to the conductor 189 shown in Fig. 22 on bay II. That is to say, this connection joins the bus and the incoming line conductor through the oil circuit breaker 190, as shown on Fig. 22, the disconnecting terminal being indicated at 194 on Fig. 22. The corresponding disconnect terminal for the other side of the circuit breaker 190 is shown at 195 on Fig. 22, and it is located in the housing or junction box 247C. A short conductor 328 which joins the disconnect terminal 195 with the main bus conductor extends through the short connection 293C shown on Fig. 19B. The horizontally extending conductor 191, shown on Fig. 21, then continues through the sheath 329 into the lateral extension 333 of a junction box 249C wherein there is disposed the disconnecting terminal 194' indicated on Fig. 22 for the circuit breaker 193 shown on said diagram, the opposite disconnecting terminal of which, indicated on the diagram as 195', is disposed in the junction box 240C on Fig. 19B, and it in turn is connected to the C phase of the reserve bus 192 through the short run of sheathing 332C leading to the junction box 253C.

The conductor 191 continues past the joint 331 in a straight run into the disconnecting terminal junction box 258C shown on Fig. 21C where connection is made with the disconnecting contacts 283 shown in Fig. 21C corresponding to the disconnecting coupling indicated at 199 in Fig. 22. A circuit extends from the disconnecting jaws 283 to the cooperating contact 334 which is mounted on a bushing 335, which forms a stationary terminal on top of the transformer unit box 259.

In a similar manner the opposite terminal of the transformer 196 connects through the bushing 336 to the contact 337 which engages the disconnecting jaws 260. The stationary terminals 283 and 260 are mounted in flanged insulating bells 338, 339 connected to the tops of corresponding insulating sleeves 340 and 341, these sleeves being conical to guide the bushings 335 and 336 into place. The upper ends of the sleeves 340 and 341 are flanged to cooperate with the flanged bells aforesaid, and the junction of these parts and electrical

connection on the conductor 191, which extends through the top of the bell and into contact with the releasable jaws 283 and 260, are all covered with either molded or wrapped insulation to insulate all live parts.

The conductor 191 is typical of other conductors throughout the system. It comprises a stranded cable of six solid strands or hollow strands wrapped around a central rod or tube, the six conductors arranged in the circular group having their ends swaged into triangular form, as indicated in Figs. 26 and 27. A spider shaped filling member 342 is disposed between the triangular ends 343 of the conducting rods or tubes 344, and thereupon a connecting casting of copper indicated at 345, is cast about the conductors 343, a star insert 342 and a suitable bolting lug 346, as shown in Fig. 26. A conductor is then provided with a wrapped insulation extending from the casting 345 over the entire length of the conductor where it makes connection with any other part. Suitable spacers or centering insulators, such as are indicated at 347 in Figs. 21A, 21B and 21C, are disposed between the insulated conductor and the metallic sheath. It is to be observed that the junction boxes in all cases have removable sides or covers to permit of the insertion of the conductor and making of joints in such junction boxes. The conductors are in general coextensive with the sheath. That is to say, the conductors are made up in length corresponding to the distance between center lines of junction boxes, and joints are made in the junction boxes either with adjacent lengths of conductors or with contacts of apparatus or other suitable terminals. The conductors may be made up in any other suitable manner, as for example, of a number of bars, which may then be joined to a clamping lug by a suitable copper casting cast in place.

The above description relating to conductor 191 for phase C in bay 2 applies as well to the conductors for phases A and B in bay 2, and likewise applies to similar connections throughout bays 1 to 6 of the station.

Bay 7 of the station is devoted to potential transformers disposed in a housing 329 for the bus 180 and 348 for the bus 192. On the circuit diagram of Fig. 22 the transformers are indicated at 200 for bus 180 and 200' for bus 192. The construction of the housings 329 and 348 is substantially like that shown at 259 in Fig. 21C. Junction boxes housing disconnecting contacts such as those shown at 283 and 260 in Fig. 21C are mounted on cantilever beams extending outwardly from the main side frames or sills 205 and 206. These potential transformers are employed in this station to provide a synchronizing connection between the station and the busses of the main generators or main generating station since the present station is merely a substation. Also these trans-

- formers provide a small output of low voltage current for local power purposes in and around the sub-station. Since the construction of these parts is substantially identical with the potential transformers shown in detail in Fig. 21C described in connection with bay 2 Fig. 19B it is not believed to be necessary to give a detailed description of them. The junction boxes 351A, 351B and 351C house disconnecting contacts which are interconnected through the short sections of sheathings 352, 353. The opposite terminals of the tension transformers are connected to disconnecting contacts mounted in the junction boxes 333A, 333B and 333C. The disconnecting contacts in these latter junction boxes are connected to the main bus 180 through sheath sections 354A, 354B and 354C. The connections of the potential transformer 200' shown at the bottom of Fig. 19G are identical with the exception that they relate to the reserve bus 192.
- Bay 7 is provided with an enclosure for housing the elevator or crane 273 and its traveling platform 270 when the same is not in use. To this end a roof or cover 355 is mounted upon the frame of bay 7 to protect the elevator and car from the weather. The sides may also be enclosed if so desired, and the end is preferably closed with a roller curtain 356 of metal slats, which is provided to permit access to the interior of the housing.
- The sheathing heretofore described in connection with this station is preferably copper tubing of hard drawn seamless character of thin walls procurable on the open market. I employ it in lengths of the order of 8 inches in diameter by 5 ft. long. The junction boxes are preferably made of non-magnetic steel or other suitable non-magnetic metal, some of the early boxes which I employed having been made of bronze. The enclosure, that is, the sheathing, the junction boxes, the space about the disconnecting contacts and the housings containing the potential transformers, current transformers, fuses, switches and disconnect switches where they are employed are all filled with a relatively thin fluid insulator, preferably a thin oil. I have employed for this purpose a lubricating oil corresponding to medium grade cylinder oil. In order to prevent excessive loss of oil in the case of the sheath being damaged or leakage occurring at any point I have arranged stop joints for the oil at suitably selected points so that the loss of oil will be confined to a relatively small part of the system at any time.
- Each bay is provided with a series of reservoirs such, for instance, as the reservoirs 357A, 357B and 357C shown in Figs. 19B and 20B in bay 2. These reservoirs serve to make up any small amount of oil loss by leakage, and serve also as expansion tanks to take in

and play out the oil due to changes in temperature of the oil.

In this connection I wish to point out that it is one of the important aspects of my invention to utilize the insulating oil and the sheathing tube as a means for dissipating any excessive heat which is caused by current flow in the enclosed conductors. Also the oil and the enclosed metallic sheath assists in avoiding the formation of hot spots at any part of the copper conductor or contacts. The high conductivity of the sheathing particularly when made of copper tube, and the fluidity of the oil are conducive to the dissipation of heat so that the temperature rise even under maximum load conditions is not excessive. This limitation of temperature rise is highly desirable in keeping down the losses in the busses and associated conductors which would otherwise occur if the copper parts were allowed to have a material temperature rise. While the change in resistance of the bus due to permissible temperature rise is not great in absolute terms, nevertheless when considered in conjunction with the large flow of current such loss, known as the I^2R loss, is important.

The reservoirs 357 are connected to the various junction boxes, and thus to the connecting sheaths by means of small bore pipes such as 358 shown in Fig. 19B and shown more clearly in Fig. 21B. The reservoirs 357 are mounted on elevated frames more clearly shown in Fig. 21B so that they maintain a gravity head upon the connected containers. Suitable gage glasses, such as 359, shown in Fig. 21B, may be employed to indicate the level of oil in the containers.

In a station comprising a considerable run of sheathing it is desirable that the sheathing be interrupted electrically in order to prevent the building up of sheath voltages which might be dangerous to the workmen or attendants, or which might cause excessive electrolysis or other injury due to such current flow, and I arrange for the interruption of such sheaths electrically by the interposition of insulating joints to restrict the induced voltage in the sheath to a sufficiently low value so that the same is not injurious. This may be done by the simple expedient of gaskets of insulating material between adjacent clamping flanges, suitable bushings being provided to insulate the bolts which would otherwise shunt such gaskets.

The conductors, it will be observed, are made up in relatively short lengths corresponding to the distance between connections in junction boxes, and due to the offsetting vertically of adjacent conductor sections, as will be apparent from Fig. 20, the sheathing may be set up substantially complete, and joined to the junction boxes; the conductor lengths are then inserted through suitable hand holes in the sides of the junction boxes,

the connections made within the junction boxes by the flexible connections, and the hand holes or openings in the junction boxes are closed by suitable cover plates. The junction boxes which house the various disconnecting contacts all have removable covers at the top so that access may be had to the interior of same.

It will be observed that each length of sheathing has its expansion joint, and each corresponding length of conductor contained therein has a flexible coupling to an adjacent length so that expansion or contraction due to heat will not adversely affect the system. At the same time the expansion permitted is sufficient to permit a weaving or expansion and contraction of the supporting steel structure. The result is a unitary structure of great durability and strength. The details of the expansion joint are shown in Fig. 25. This shows also the connection of the ends of adjacent copper tubing forming the sheath. The copper tubing 360 shown in Fig. 25 has a flange 361 formed thereupon. A ring 362 on the back side of the flange is disposed on a tube before the flange 361 is formed. A bolting flange member 363 has an outwardly extending bolting flange 364 for cooperating with a flange 365 which is anchored to the flexible metallic tube 366. The flange member 363 has piloting projection 367 extending into the open end of the tube 360. The telescopic member 368 which bears flange 365 has a tubular extension 369 extending inside of the telescopic member 370. The flexible diaphragm member 366 has extending ends at 371 and 372 which are clamped between clamping means 373, 374 and shoulders on the corresponding telescopic members 370 and 368, as indicated at 375 and 376, the ends of said flexible diaphragm member 366 being soldered to said ring members. The telescopic member 370 in turn has bolting flanges 377 cooperating with the flanges 378 of a connecting member 379 which is identical with the member 363, and the tube 380 likewise has a flange 381 held by means of a clamping ring 382. Fig. 25 shows the expansion joint as disposed in a run of sheathing connected at both ends. I prefer generally to bolt one of the flanges 377 or 365 to the flanges of a junction box so that the expansion joint is supported directly from the junction box instead of being supported in the run of tubing on each side. In other words, the member 379 shown in Fig. 25 may be a part of the junction box so that the joint finds a firm support thereon. The outside of the diaphragm is loosely covered by a thin cylinder of sheet metal indicated at 383 to protect the diaphragm 366 from the weather and from accidental injury.

Figs. 23 and 24 show a typical arrangement in a station embodying my invention. In this case the columns or posts are indi-

cated at 384 and 385 at opposite sides of the longitudinally extending main frame, which is indicated generally at 386, connected to the top of said posts 384 and 385. In this case the incoming line, one phase of which is shown in Figs. 23 and 24, enters as the cable 387 extending up along the side of the post 384 to the pothead 388 where the same is joined to the bottom of a current transformer and pothead housing 389, this housing being supported on the sides of the main frame 386 as by means of longitudinally extending channel bars 390. This housing 389 extends up above the main frame 386 so as to provide a connection transversely of the main frame for the run of sheathing 391 which houses the conductor for the incoming line forming an extension of the cable 387. The conductor from the cable 387 extends through the current transformer 392 to the horizontal conductor 393, and this conductor 393 extends to a coupling 394 where a laterally extending conductor 395 in the housing 396 joins the disconnecting contact 397. From the coupling 394 a continuation of the conductor 391, which preferably is a separately manufactured conductor 398, extends through the sheath 399 from the junction box 396 over to another coupling member 400 where a laterally extending conductor 401 makes connection with the disconnecting contact 237 in the junction box 403. From the coupling 400 a conductor 404 in line with the conductor 398 extends through the sheath 405 over the reserve bus 406 to the disconnecting contact housing 407 which contains disconnecting couplings or contacts for potential transformers.

The main bus shown at 408, Fig. 23A, lies on the same horizontal level as the bus 406, and the cross connection which has just been described extends in a plane above the main and reserve busses. This cross conductor, which is one of the phase conductors of the line connection, is connected to a corresponding phase conductor of the main bus and the reserve bus through the oil circuit breakers 231 and 232 respectively, suitable disconnecting contacts being provided for said circuit breakers as heretofore described in connection with Fig. 23B. The housing 409 on Fig. 23A contains a disconnecting contact for the circuit breaker 231, which disconnecting contact is connected by a conductor 410 extending through the sheath 411 to a junction box 412, in which through the coupling 413 connection is made with the corresponding bus conductor 414.

The corresponding disconnecting coupling 238 in the housing 415, shown in Fig. 23B, is connected to the bus conductor 416 by a short run of conductor 417 and coupling 418 in a junction box 419.

The oil circuit breakers 231 and 232 have their operating mechanism indicated at 420

and 421, these being raised and lowered with the circuit breakers. The circuit breakers are supported from the main frame 386 by suitable means which lock the circuit breakers in place, such means being indicated generally by the brackets 422 on Figs. 23A and 23B. Suitable means is preferably provided to permit manual lowering of the circuit breakers to disconnect the contacts such as 10 233, 237 and 234, 238. By this means it is possible to disconnect a line by the removal of the circuit breaker as a link, and if it is desired to inspect or open the circuit breaker, it is then lowered by the elevator mechanism heretofore described.

I have not shown the reactors nor the transformers to be used in connection with this particular embodiment, but as previously explained, they are disposed at the sides 20 of the station in line with the bays to which they are connected, transformers and reactors being treated alike in this regard, and then being connected to the station structure through the cables, such as 315 shown in Fig. 25 21A.

In Fig. 20B I have shown the three single-phase cables 423A, 423B and 423C coming up from underground through the reenforced conduits 424A, 424B and 424C. 30 These reenforced conduits preferably comprise tubes wrapped with rope or cord impregnated with cement and finished with neat cement on the outside to protect them from accidental damage at or near the 35 ground level. All of the joints are taped with varnish cambric tape to the desired thickness and then faced with binding tape or friction tape so as to insulate the joints with sufficient insulation so that in case of 40 loss of oil, damage to the station would not occur.

The stop joints for limiting the escape of oil may constitute merely flexible packing disposed between the insulation of the conductor and the sheath or the neck of the junction box at suitable points.

The centering spools or insulators, such as 347 shown in Fig. 21, are shown a little more clearly in Fig. 23. They comprise similar 50 cylindrical portions having external grooves at the ends, in which grooves a suitable string or cord is wrapped to hold the halves of the cylinder of insulation together. I have not shown the low tension connections 55 for operating the circuit breaker operating mechanism and the like, but this may be suitably disposed on a framework, likewise the instrument connections, but it will be obvious to one skilled in the art that they may 60 be suitably disposed on the frame.

While I have disclosed the use of copper tubes as forming the sheathing, I may make up a pipe of sheet metal in which the cross section is rectangular or any other desired 65 section, and it may consist of a substantially

closed cylinder with the non-magnetic strip welded along the side to close the cylinder.

It will be observed that the spacing of conductors to the ground and between phases is less than that generally employed for exposed conductors. In other words, it is permissible with this invention to dispose high tension parts or conductors closer to each other than is considered good practice according to any other system.

I do not intend to be limited to the precise details shown or described, as the invention is capable of being embodied in a great variety of embodiments and in sizes without a limit. While the station which I have thus described above is designed for 33 kv., there is no inherent limitation in the design to keep it from being employed for any desired voltage, and at present the State line station is being built as an embodiment of this invention operating on 132 kv.

It is to be observed in the embodiment of Figs. 19 to 28 inclusive that the line bus conductors and their sheaths are all disposed on substantially the same level as may be observed from the cross section of the station shown in Fig. 21. By this means the junction boxes at the line side of the station, which junction boxes connect with the pot-heads of the cables and contain the current 95 transformers, are all disposed on a common level and may all be identical.

In a like manner the junction boxes for the disconnecting terminals of the potential 100 transformers at the opposite side of the station may all be alike, and all connected on the same level and identical in construction. The bus conductors of both the main bus and the reserve bus are disposed in planes alternately above and below the plane of the line 105 bus conductors and are joined by the flexible joints or connections shown more specifically in Figs. 28, 20B and 20E. The disconnecting terminals for the line switches are all arranged on the same level and may all be 110 duplicates since there is no change in dimensions throughout the station.

It will be apparent that if desired the buses may be sectionalized by interposing 115 circuit breakers, and such circuit breakers could be disposed in a bay in a manner similar to the line circuit breakers thus far shown.

It will be observed that the flexible connections illustrated in Figs. 20D and 20E comprise a portion extending substantially vertically to make connection from the transverse conductors to the longitudinal conductors. Where the bus conductor is disposed above the line conductor, as will be apparent in Fig. 20C, the junction box is reversed as compared with its position in Fig. 20E, since in Fig. 20C, that is, in the bay III, the bus conductor is disposed in a plane above the plane of the line conductor, whereas in bay 120

V the line conductor is disposed in a plane above the bus conductor.

It will be observed that the main bus conductor is sub-divided into sections which are 5 joined by three-way sections, two arms of which are flexible and one of which is substantially rigid. The sheaths for the main bus conductors at each bay are provided with 10 expansion joints so that a sufficient flexibility and expansibility of the bus and its conductor and sheath are provided for. The line bus conductors which extend transversely of the station at each bay also have their sheaths provided with expansion joints, but the run 15 of the conductor itself is so short that no expansion joint is required. It will be observed that the joints to the circuit breaker disconnecting terminals are made by short lengths of conductors such as 395 and 401 in 20 Figs. 24A and 24B, so that any slight displacement of the line bus conductor would not put any serious stress upon the disconnecting terminals. Also the left-hand end of the line bus conductor, as shown in Fig. 21A, 25 is connected to the cabled conductor 315 at right angles of the current transformer so that the expansion and contraction of the line bus conductor is able to occur without any inconvenience to the electrical connections or 30 the mechanical connections. By the provision of the expansion joints in the sheath, the flexible joints in the conductor, and the use of a liquid dielectric it is possible to let the structure have considerable movement, due 35 either to temperature changes or movement of the frame, without impairing the electric connections or disturbing the insulation of the conductors.

In the construction of the above described 40 station, namely Wheaton sub-station, it has been found that due to the requirement to assemble many of the parts in the field the erection of the station is delayed, and expensive field labor is required to perform operations and assemblies that could be more 45 cheaply and expeditiously done under factory conditions by factory labor. I have, therefore, devised a modification shown in Figs. 29 to 32 in which the elements may be 50 integrated into larger units assembled in the factory, and then set in place on the frame in the field, and all that is then required is that a few joints be made up in the field.

In the modification shown in Figs. 29 and 55 30 I provide a steel frame made up of the posts 425 and 426, these posts being disposed in longitudinal rows and being connected by cross beams such as 427 and 428 (see Fig. 29).

60 A single bay is illustrated in Figs. 29 to 31, and this bay is made up of a single circuit with so much of the main and reserve buses as is required to cover or extend through the bay. Circuit breakers and instrument 65 transformers are provided for the bay.

Preferably I employ the circuit breaker terminals with their housings, the sectional conductors of the main bus and sectional conductors relating to the line bus in a unit which may be assembled readily in the factory, shipped to the site, set up in place, and connected in the field. 70

I may assemble all of the essential elements of a single bay at the factory and ship the unit to the site for setting in the frame, but at present I prefer to make the largest unit and assembly of the circuit breaker terminals part of the line connection thereto and part of the bus corresponding to a single 75 bay. 80

Referring now to Figs. 29 and 30, to make up the assembled unit just described I provide a base plate 430 upon which are mounted housings for the quick detachable connectors of the three oil switches 431A, 431B and 431C. These housings are provided in pairs, the housing 432A being provided for the bus terminal of the oil circuit breaker 431A, and the housing 433A being provided for enclosing the quick detachable connector for the oil circuit breaker 431A which is to be joined to the line bus. In like manner the housings 432B and 432C are connected to the corresponding phases of the main bus, and the housings 433B and 433C contain the quick detachable connectors for the oil circuit breakers joined to the line bus conductors of the corresponding phase. 85 90 95

These housings with their enclosed quick 100 detachable connectors of the type shown, for example, in Fig. 21C are mounted directly upon the unit frame 430. The plate 430 which forms a part of the unit frame is in turn connected at its edges to a pair of longitudinally extending beams 434 and 435, and between these beams 434 and 435 the oil circuit breakers 431 are disposed and mounted. The longitudinal beams and the top plate 430 form a frame sufficiently rigid to be assembled in the factory, shipped to the site and thereupon mounted on the elevated frame including the posts 425, 426 and the cross beams 427, 428. The beams 434, 435 are connected at their ends to the cross beams 427, 428 by suitable field assembly. 105 110 115

The housing 433A has a lateral opening extending towards the top of Fig. 29 where it is connected by a suitable junction box 436A to the sheathing for the transverse line conductor of the A phase. Likewise the housing 433B is joined to a junction box 436B by companion flanges about registering openings in these parts, and the junction box 436C likewise is joined to the housing 433C. Incoming line conductors in the form of underground cable extend up through conduit 437 as shown in Fig. 30 along the sides of the row of posts 425, this single phase cable 438 having an end bell 439 by which its sheath is joined to the current 120 125 130

transformer housing 440. Each such single phase cable is the same as the particular cable 438C illustrated in Fig. 30 and entering the current transformer and fuse housings 440, which housings may be supported on short cantilever beams extending from the sides of the beams 434, such cantilever beams being omitted for the sake of clearness.

- 10 From the current transformer and fuse boxes 440 short runs of sheathing 441A, 441B and 441C extend over to the corresponding junction boxes 436A, 436B and 436C. This sheath may be a permanent assembly or 75
15 it may be separable on the flanges 442 shown in Fig. 29.

The longitudinal bus conductors are disposed in suitable relation above the plate 430, the sheath therefor being joined to the 20 bus side of the circuit breakers 431 as follows:

A sheath for the A phase indicated generally at 443A is joined to the upper part of the housing 432A which contains the quick 25 detachable connector for the oil circuit breaker 431A for making connection from the bus conductor through the oil circuit breaker to the corresponding line bus conductor housed in the sheath 441A.

30 The bus conductor which is contained within the sheath 443B is joined to the corresponding oil circuit breaker 431B through the quick detachable connector which is housed in the housing 432B. The sheathing 35

443B joins opposite sides of the junction box 444B. This junction box 444B is connected to the housing 432B by companion flanges so that this junction box 444B and the corresponding housing 432B may contain a short 40 lateral connection from the bus conductor to the corresponding terminal of the quick detachable connector for the oil circuit breaker.

In a similar manner the sheathing which 45 contains the C phase bus conductor, namely, the sheath 443C, is joined to opposite sides of the junction box 444C. This junction box being joined laterally to the housing 432C to house a short conductor laterally joins the 50 corresponding bus phase conductor with the quick detachable connector of the corresponding oil circuit breaker 431C.

The ends of the sheaths 443A, 443B and 55 443C are provided with junction boxes illustrated in detail in Fig. 32. These junction boxes are alike and a description of the same in connection with Fig. 32 will suffice for all three phases of the main and reserve bus. Assuming that the construction illustrated 60 in Fig. 32 belongs in the B phase of the main bus, the sheath 443B at the left of Fig. 32 is connected to the junction box 446. Said junction box 446 comprises a neck 447 having an internal groove 448 into which the wall 65 of the sheathing tube 443B is expanded to

provide a mechanically rigid joint. The joint may be made fluid-tight by this expansion, but I prefer to insure the fluid-tightness thereof by sweating or soldering these two parts together.

The upper part of the junction box 446 has an opening surrounded by bolting flange 449 adapted to be connected to a cover plate 450 through the removal of which access to the interior may be had. The opposite end of 75 the box 446 has an opening of a larger diameter than the opening in the neck 447, and this opening is surrounded by a coaxial cylindrical flange 451 to which may be connected the corresponding cylindrical end 452 of a 80 collapsible metal bellows 453 as by means of a soldering band 454 which is wrapped around the flange 451 and the corresponding flange 452 of the corrugated diaphragm 453.

The opposite end of the corrugated diaphragm 453 is embodied in a molded ring 455 to form a tight joint. The ring 455 may be divided into two parts having cooperating flanges where it is desired to divide the run of sheathing between the two corrugated bellows 453 and 456. The copper tubing 457 forming a part of the sheathing for the B phase of the next adjacent bay is joined in a similar manner to the box 458, which box 458 is in all material respects identical with the 95 box 446; in fact it is intended that but one pattern is required for this type of junction box through which the adjacent bays are connected.

The corrugated copper diaphragm 456 is 100 joined to the junction box 458 in the manner heretofore described and connects with box 446 through the ring 455 and connected bellows 453, and a suitable cover member 459 is secured to the flange about the opening of the box 458. The conductors which make up the main bus are cut to a suitable length to terminate in the junction boxes such as 446, 458 at the ends of the bays and when the sheathing is joined up as for example by soldering the ends of the corrugated diaphragms 453 and 456 to the adjacent flanges of the junction boxes a joint in the conductor which bridges the gap between the ends of such conductors as 460 and 461 shown in 110 Fig. 32 is made by a short piece of conductor 462 as by the clamp connectors 463 and 464. As indicated in dotted lines in Fig. 32 the short section 462 which bridges the gap between conductors 460 and 461 may be put in place through the open top of one of the junction boxes 446 or 458.

An oil barrier 465 is shown in Fig. 32 as 115 introduced within the cylindrical flange 451 on junction box 446. This barrier or diaphragm comprises a circular plate having packing rings such as 466 disposed in grooves on its outer periphery and bearing against the inner wall of the flange 451. In like manner 120 packing such as 467 may be disposed in 125

grooves formed in the inner periphery of the diaphragm 465 and bearing against the exterior surface of the insulation of the short conductor section 462. Thus by the connection shown in Fig. 32 the sheaths and conductors of the main bus and of the auxiliary bus may be joined from bay to bay and the three junctions of an expansion joint, an insulating joint and oil barrier or diaphragm 10 embodied at this point.

The bus conductor in the A phase, as may be seen from Figs. 29 and 30, extends in a continuous run throughout the length of the bay, this phase lying beside the B phase. To 15 make connection between the conductor of the A phase and its corresponding line bus conductor requires a connection from the bus phase conductor to the quick detachable connector for the oil circuit breaker in the housing 432A from whence the connection extends through an oil circuit breaker 431A to the connector in the housing 433A from the terminal of which a short conductor extends over to the line phase conductor where a 20 joint is made in the junction box 436A.

The B phase lies outside of the A phase and directly above the C phase. The connection from the conductor of the B phase to its corresponding line bus conductor is made by 25 a short connection extending downwardly in the junction box 444B and then laterally in the horizontal plane common to the line bus conductors in the sheaths 441A, 441B and 441C. This lateral connection is then joined 30 to the quick detachable connector of the oil switch 431B. The circuit then extends through the oil switch to the quick detachable connector in the housing 433B, and from the terminal of said connector a short run of conductor extends to the line bus conductor by a 35 joint made in the junction box 436B.

The connection between the C phase bus conductor and its corresponding line bus conductor in this bay is made by a short connection 40 extending upward vertically in the junction box 444C, then laterally into the housing 432C where a joint is made with the quick detachable connector for the bus side of the oil circuit breaker 431A. The circuit then extends 45 through the circuit breaker to the connector in the housing 433C from the terminal of which a short conductor extends horizontally into the junction box 436C and makes 50 connection with the line bus conductor in the sheath 431C.

Now it is to be observed that the line bus conductors and their sheaths lie in the same horizontal plane, and that the terminals of the connectors for the oil circuit breakers lie 55 in the same plane, thereby producing short direct connections throughout.

The transformer and fuse box 440 in each line bus conductor contains an additional connection, as may be seen in Fig. 31, extending 60 to the potential transformers 468 dis-

posed in housings 469A, 469B and 469C. In the line diagram of Fig. 31 the potential transformer is indicated at 468 and the connection to the line bus conductor 470 is made at a point on the line side of the current transformer 471.

The housings for the potential transformers are mounted upon a suitable mounting plate 472 supported on longitudinal beams 473 and 474, which in turn are joined at their ends to the transverse beams 428 and 427. The potential transformer housings with the contained transformers may be mounted on a plate 472 as a unit assembly and shipped to 70 location for setting and connection. These housings 469A, 469B and 469C are connected through flanged couplings 475A, 475B and 475C to the corresponding conductor sheaths 476A, 476B and 476C extending over to the current transformer and fuse boxes 440A, 440B and 440C respectively, and there joined to said boxes through suitable clamping flanges or the like.

If desired, the potential transformer bank and the circuit breaker and bus bank may be 80 assembled in the factory and shipped together.

The reserve bus shown at the right of Fig. 29 may be made up in a manner substantially identical with that described in connection 85 with the main bus. The connection to the incoming line is a continuation of the sheath 441A, 441B and 441C which I have designated as 477A, 477B and 477C. This sheath may be joined to the corresponding junction 90 boxes 436 and 478 by flanged couplings as indicated in Fig. 29, or the entire run of bus and sheath may be made up permanently and disconnected on the flanges between the junction boxes 436, 478 in the corresponding housings 433 and 479.

The entire bay may be connected together by suitable framework assembled in the factory and shipped in the assembled form to be 100 mounted on the elevated frame, and then connections need be made only as between the base and between the line bus conductors and the cable conductors for the line. The arrangement shown in Figs. 29 and 30 allows 105 for a much more compact grouping of the necessary elements with consequent saving of material and space. The oil reservoirs or conservators indicated at 480 and 481 for the main bus and the reserve bus are mounted on the corresponding units with suitable piping 110 connected at the factory. In the diagram of Fig. 31 the main bus conductor is indicated at 482 and the reserve bus conductor at 483, the main circuit breakers at 431 and the reserve circuit breakers at 484, the short conductors 115 extending from the main bus conductor 482 to the main bus terminal of the oil circuit breaker at 485 and the short connection from the line side of the circuit breaker 431 to the line bus conductor 470 at 486.

120

125

130

Likewise the connection from the reserve bus conductor 483 to the oil circuit breaker as indicated at 487 and the connection from the reserve oil circuit breaker to the intermediate section 488 of the line bus conductor 470 is indicated at 489. I believe that with the diagram of Fig. 31 and the explanation heretofore given the disposition of the conductors within the sheaths will be perfectly clear.

Obviously various rearrangements of parts and details may be made within the spirit of the present invention. It will be seen that by disposition of the elements upon a unit frame the expansion and contraction of the elements on a given frame is not as important as the likelihood of expansion and contraction between bays, and I have, therefore, provided the expansion joints in the bus conductor sheaths at the point where joint is made between bays. The joining of sheaths to junction boxes may be made much more efficiently and cheaply where the unit construction is employed, as above described, since the expanded copper tubing joins the necks of the junction boxes more effectively than could be attained by providing special clamping flanges. It will be observed that according to this scheme the bus phase conductors extend continuously without the offset up and down which the earlier form requires. This is a distinct advantage. If an expansion joint in the conductor is required the same may be readily inserted in one of the junction boxes or in one of the joints between bays.

I do not intend to be limited to the details herein shown or described, but desire to avail myself of such variations as come within the scope of the appended claims.

I claim:

1. In a system of the class described, a conductor for electricity, a thin metal tubing forming a fluid tight insulation containing sheath for said conductor and a rigid metallic frame member comprising structural steel bars disposed substantially coextensive with the sheath and providing mechanical support and rigidity for the sheath and for its contained conductor.
2. In a three phase system of the class described, a plurality of junction boxes for each phase, phase conductors joined in said junction boxes, tubular sheathing members individual to each phase loosely enclosing said conductors and extending between said junction boxes, said tubular sheathing members being sufficiently rigid to be supported from said junction boxes, supporting means engaging the junction boxes and supporting the conductors and sheathing members through the junction boxes, said junction boxes and tubular members providing fluid tight sheathing individual to each phase, and adapted to contain fluid insulation, and expansion tanks connected to the sheathing of

each phase for keeping the sheathing and junction boxes filled with liquid insulation.

3. In a system of the class described, a plurality of junction boxes, conductors extending between and joined in said junction boxes, tubular sheathing members loosely enclosing said conductors and extending between junction boxes, said tubular sheathing members being supported by said junction boxes, and a rigid metallic frame supporting said junction boxes in fixed relative position.

4. In a system of the class described, a rigid supporting frame formed of metallic members connected to ground, a plurality of junction boxes fixedly mounted on top of said frame, conductors extending between and joined in said junction boxes, sheath members carrying insulating fluid extending between said junction boxes and enclosing said conductors, and circuit breakers depending from said frame and joining said conductors.

5. In a system of electrical power transmission, the combination of a conductor, a thin tubular metal sheath loosely surrounding the same, and a grounded structural steel frame coextensive with the sheath and secured thereto, said frame supplying the necessary strength and rigidity for supporting the sheath and the conductor.

6. In a system of electrical power transmission, the combination of a conductor, a thin tubular metal sheath loosely surrounding the same, insulation for the conductor, means centering the insulated conductor in the sheath, a grounded structural iron frame co-extensive with the sheath and secured thereto, said frame supplying the necessary strength and rigidity for supporting the sheath and the conductor, and a filling of insulating liquid in said sheath.

7. The combination of a series of relatively short tubular sheath members containing insulating fluid, junction boxes joining adjacent ends of the sheath members and supporting the same, a series of relatively short conductor sections joined in said junction boxes and supported in said sheath members and in said junction boxes, and a structurally independent frame supporting said junction boxes.

8. The combination of a series of relatively short thin tubular sheath members, junction boxes joining adjacent ends of the sheath members and supporting the same, a series of relatively short conductor sections joined in said junction boxes and supported in said sheath members and in said junction boxes substantially centrally of said tubular sheath members, a structurally independent rigid grounded metal frame supporting the junction boxes and a filling of insulating liquid in said sheath members and junction boxes.

9. In combination, a series of relatively

short tubular sheath members carrying insulating fluid, junction boxes joining adjacent ends of the sheath members and supporting the same, a series of relatively short conductor sections having clamping lugs at their extremities, adjacent ends of said conductors being joined in said boxes, said conductors being supported in insulated relation in said sheath members, and a structurally independent frame supporting said junction boxes.

10. In combination, in a bus system, a series of junction boxes, short lengths of straight rigid tubing joining said junction boxes, said tubing being supported by said junction boxes, a series of conductor sections extending from junction box to junction box and joined therein, said conductor sections being so short relative to their length that they are not appreciably flexible, insulating means for centering the conductors in the tubing, and a filling of insulating liquid for said tubing and said junction boxes.

11. In combination, a longitudinally extending framework, a plurality of transverse bus troughs disposed on said framework, junction boxes disposed on said troughs and communicating therewith, longitudinal sheath members joining the junction boxes and supported thereby, bus conductors in said sheath members joined in said junction boxes, and connecting conductors joined to the bus conductors in said junction boxes and extending into said bus troughs, said sheath members, said junction boxes and said bus troughs being filled with insulating liquid.

12. In combination, a trough member, contact sockets mounted on the bottom of the trough member for connection with detachable terminals of a circuit breaker, a junction box on said trough member and having communication therewith, sheath members communicating with the junction boxes, conductors in said sheath members, said conductors extending into the trough members and connecting with said contact sockets, and a filling of insulating liquid for said sheath members and said trough members.

13. In combination, a longitudinally extending framework, a plurality of trough-like boxes extending transversely of said framework, junction boxes mounted on the ends of said boxes and communicating therewith, longitudinally extending tubular sheath members joining the junction boxes, bus conductors extending through said sheath members and joined in said junction boxes, line conductors entering said boxes, separable circuit breaker coupling terminals mounted on the boxes for external connection of circuit breakers, a conductor in one of said boxes joining the line conductors to one of said coupling terminals, and a conductor joining another of said coupling terminals with the bus conductor, said latter

conductor extending from the box into the corresponding junction box.

14. An electric bus and switch station comprising an elongated framework, posts supporting said framework in an overhead position, buses supported in insulated relation above said framework and lengthwise thereof, line conductors also supported in insulated relation above said framework and generally crosswise thereof, disconnecting terminals for the lines and buses mounted in insulated relation on said framework, and circuit breakers suspended from the framework and having terminals cooperating with said disconnecting terminals, and grounded sheathing for said buses, line conductors and disconnecting terminals including the insulation thereof, said sheathing being mounted on said framework.

15. A bus and switch station comprising a structural frame, posts supporting the same in elevated position, said frame being divided into bays, a longitudinally extending main bus common to the bays, said bus comprising phase conductors, transversely extending line buses comprising phase conductors, each line bus being individual to a bay, circuit breakers suspended from the frame adjacent the overpass of the line bus and main bus and adapted to connect the line bus and main bus, junction boxes housing the connections of the circuit breakers and the line bus and main bus, individual sheathing covering the phase conductors of the main bus and line bus and joining said junction boxes, said sheathing and junction boxes containing a liquid dielectric, a line comprising single phase cables extending from underground to the overhead frame along the side of the frame, and junction boxes in which the cable conductors and line bus conductors are joined.

16. In a bus and switch station, the combination of an overhead frame, a multi-conductor bus extending longitudinally of the frame, line conductors extending transversely of the frame disposed in a horizontal plane out of the plane of the bus conductors, disconnecting terminals mounted on the frame adjacent the overpass of the line and bus conductors with respect to each other, metal sheathing grounded on the frame individually enclosing the bus conductors and line conductors, liquid insulation means for said sheathing and circuit breakers having cooperating disconnecting terminals, said circuit breakers being movably supported on the frame.

17. In a bus and switch station, the combination of a longitudinally extending frame, a main bus extending longitudinally along one side of the frame, a reserve bus extending longitudinally along the other side of the frame, means for supporting the frame along its sides, transversely extending line bus conductors disposed in a plane out of the plane

of the main and reserve bus conductors, disconnecting contacts mounted on the frame between the main bus conductors and the reserve bus conductors, said contacts having connection with the lines and with the buses respectively, and oil circuit breakers bearing disconnecting contacts cooperating with the aforesaid disconnecting contacts suspended from said frame and adapted to control the connection between the lines and buses.

18. In combination, a longitudinally extending bus divided into sections, transversely extending lines, said lines being disposed all in a common plane, the sections of the bus being disposed in planes alternately above and below the plane of the lines, circuit breakers for controlling the connection between lines and the bus disposed at points of proximity of the line conductors to the bus conductors, and flexible connectors joining adjacent ends of sections of the bus and electrically connected to the terminals of the oil circuit breakers.

19. In combination, a longitudinally extending bus comprising sections alternately disposed on different horizontal levels, lines having conductors extending transversely of the bus conductors, all disposed on a common level intermediate the level of the bus conductors, flexible connections joining adjacent sections of the bus conductors, and circuit breakers connected to the bus through the said flexible connections and to the lines for controlling the connection of the lines to the buses.

20. In a station of the class described, the combination of a longitudinally extending frame divided into bays, supports along the sides of the frame for supporting the frame in overhead position, longitudinally extending bus conductors disposed along one side of the frame and comprising sections disposed on different levels, line conductors disposed transversely of the frame, each bay being devoted to conductors of a particular line, groups of junction boxes in each bay housing the adjacent ends of sections of the bus conductors, flexible conductors joining the ends of the bus conductors in said junction boxes, the line conductors of a given line being joined to the bus conductors in said junction boxes through said flexible connections, and circuit breakers suspended from the frame and having terminals mounted on the frame and connected to the lines and to the bus conductors respectively.

21. In a bus and switch station, the combination of an overhead frame, a main bus comprising longitudinally extending bus conductors on one side of the frame, a reserve bus comprising longitudinally extending bus conductors at the other side of the frame, the bus conductors being divided into sections joined together, junction boxes enclosing said joints, sheaths for the individual con-

ductors of the bus joining said junction boxes, stationary disconnecting circuit breaker terminals mounted on a frame in a longitudinal row adjacent the junction boxes of the bus conductors for the main bus and the reserve bus, junction boxes housing said circuit breaker disconnecting terminals, and sheaths joining the junction boxes of the circuit breaker disconnecting terminals with the junction boxes of the bus conductors, companion disconnecting terminals for the oil circuit breakers disposed adjacent to the first named disconnecting terminals of the circuit breakers, housings for said cooperating disconnecting terminals, said housings having lateral extensions, circuit breakers suspended from the frame and disconnecting terminals adapted to be connected to said stationary disconnecting terminals, line conductors extending into the lateral extensions of the aforesaid housings, sheaths enclosing said line conductors and joining said housing extensions, said line conductors extending in substantially straight lines transversely of the frame, said sheaths and housings of the junction boxes being filled with liquid dielectric.

22. A longitudinally extending frame, supports along the sides for supporting the same in overhead position, said frame being divided into bays, a bus extending longitudinally of the frame and disposed adjacent one side thereof, said bus comprising three-phase conductors formed in sections, the sections being joined by flexible connections having vertically extending portions, some of the sections being disposed in one horizontal plane and others of the sections being disposed in a different horizontal plane, line phase conductors individual to a bay lying in a horizontal plane between the horizontal planes of the sections of the bus, junction boxes enclosing the connections of the bus sections, metallic sheaths joining adjacent junction boxes, said sheaths including expansion joints, incoming line conductors extending vertically along one side of the frame and joining the aforesaid line bus conductors, junction boxes enclosing said joints, disconnecting terminals mounted in pairs on the frame, circuit breakers connecting said pairs of terminals, one terminal of each pair being joined to an adjacent bus conductor by a transversely extending conductor, housings for said terminals, sheaths joining said housings to the junction boxes of the line bus conductors and enclosing the last named conductors, housings having laterally extending portions enclosing the cooperating terminals of the pairs of terminals above recited, the line bus conductors extending through said lateral extensions, sheaths enclosing the line bus conductors and joining said housing extensions, and short conductors in said housing extensions joining the line bus conductors with the cooperating

- terminals, said junction boxes, sheaths and housings being filled with liquid dielectric.
23. The combination in a station of the class described, of a longitudinally extending frame sub-divided transversely into bays, a longitudinally extending bus for the frame and transversely extending lines for the bays, the bus comprising phase conductors sub-divided into sections, the line comprising bus conductors disposed on the frame, and line conductors extending vertically and joined to the line bus conductors at one side of the frame, junction boxes disposed at one side of the frame and enclosing the joints between the line conductors and the line bus conductors, the sections of the bus conductors being disposed in different horizontal planes and the line bus conductors being disposed in a common, intermediate horizontal plane, junction boxes enclosing the ends of sections of the main bus conductors, three-way connections in said junction boxes comprising two flexible arms joining the adjacent lengths of main bus conductors and a transversely extending arm for making connection with line bus conductors, circuit breaker terminals mounted on the frame and connected to the third arm of said three-way connections, cooperating circuit breaker terminals joined to the line bus conductors, and circuit breakers suspended from the frame and removable below the frame connecting said circuit breaker terminals, the main bus conductors and the line bus conductors and the connections between the main bus and the circuit breaker terminals being all enclosed in sheathing filled with liquid dielectric.
24. In a bus and switch station, the combination of a longitudinally extending frame sub-divided transversely into bays, lines for the bays comprising incoming line conductors extending in a direction transversely to the frame, the longitudinally extending bus comprising bus conductors sub-divided into sections, said sections extending between bays and being joined in the bays, adjacent lengths of conductors being disposed on different levels, line bus conductors disposed at an intermediate level with respect to the main bus conductors, three-way flexible connections joining adjacent lengths of main bus conductors and line bus conductors, junction boxes enclosing said three-way connections, metallic sheaths enclosing the line bus conductors of the main bus conductors and being connected to said junction boxes, said sheaths and junction boxes being filled with liquid dielectric, and circuit breakers suspended from the frame connected in series with the line bus conductors.
25. In combination a longitudinally extending frame, columns supporting the frame in overhead position, the frame being sub-divided transversely into bays, a main bus extending longitudinally of the frame and supported upon the same, said main bus comprising phase conductors sub-divided into sections, said sections being insulated except at their ends, junction boxes mounted on the frame and disposed in groups within the bays and enclosing the ends of adjacent conductor sections, three-way flexible connectors enclosed in the junction boxes and connecting adjacent ends of conductor sections, short lateral conductors joining the flexible three-way connections, lines for the bays comprising transversely extending line bus conductors reaching across the main frame, junction boxes disposed at one side of the main frame, incoming single-phase cables entering the last named junction boxes and joining the line bus conductors therein, the housings at the opposite-side of the station enclosing the opposite ends of the line bus conductors, potential transformers having connections in the last named housings to the line bus conductors, oil circuit breakers suspended from the frame and having terminals connected to said short conductors and to the line bus conductors intermediate the ends of the line bus conductors, metallic sheathing enclosing the main bus conductors, the short conductors and the line bus conductors joining said junction boxes and housings, said sheathing, junction boxes and housings being filled with liquid dielectric.
26. A longitudinally extending frame having supporting means along its sides supporting the same in overhead position and sub-divided into bays for lines, said line bays comprising current transformer housings at one side of the bay, current transformers therein, potential transformer housings at the other side of the bay, potential transformers in said latter housings, individual cabled line conductors entering the current transformer housings, line bus conductors extending transversely of the bay from the current transformer housing to the potential transformer housing, individual metallic sheaths for said line bus conductors joining the current transformer housings with the potential transformer housings, a longitudinally extending main bus disposed on the main frame, said bus comprising individual phase conductors, separate metallic sheaths for said phase conductors, joints in said phase conductors, junction boxes in the sheaths enclosing the joints in the phase conductors, junction boxes in the sheaths of the line bus conductors, oil circuit breakers suspended from the frame and connected to the line bus conductors and the main bus conductors through the junction boxes in the sheaths of the same, said sheaths and junction boxes and housings being filled with liquid dielectric.
27. A longitudinally extending conductor sub-divided into sections, some of said sections being disposed on a different level from

- others of said sections, laterally extending conductors, three-way flexible connectors joining adjacent ends of longitudinally extending sections and laterally extending conductors, junction boxes enclosing the ends of adjacent conductor sections and the ends of laterally extending conductors and housing the three-way connections, tubular metallic sheaths joining the junction boxes and comprising expansion joints, said sheaths and junction boxes being filled with liquid dielectric.
28. In a bus and switch structure comprising a steel frame for supporting a longitudinally extending conductor comprising sections, laterally extending taps at the ends of adjacent sections, flexible three-way connectors joining adjacent ends of the longitudinally extending conductors and the ends of the laterally extending taps, junction boxes enclosing said connectors, tubular sheaths including expansion joints connecting adjacent junction boxes, and a filling of liquid dielectric for the sheaths and junction boxes.
29. In a bus and switch station, a longitudinally extending overhead frame, posts supporting the frame, a longitudinally extending bus mounted on the frame, incoming lines comprising single phase cables extending from the underground to the overhead frame, circuit breakers suspended from the frame for controlling the connection of the lines to the bus, transversely extending line bus conductors connected through the single phase cables to the main bus conductors in series with the circuit breakers and individual metallic sheaths for each of the line bus conductors grounded on the frame and filled with insulating oil.
30. In combination, a longitudinally extending frame, columns supporting the frame in overhead position, a main bus extending longitudinally of the frame and supported on top of the same, said frame being divided transversely into line bays, the main bus comprising separate phase conductors divided into sections extending between bays, junction boxes enclosing the ends of adjacent main bus conductor sections, three-way connectors joining adjacent ends of the sections of the main bus conductors, laterally extending conductors also joined to said three-way connections, individual metallic sheaths for the line bus conductors joining the junction boxes of adjacent bays, said sheath and junction boxes being grounded on the frame, transversely extending line bus conductors disposed transversely on the frame and having individual metallic sheaths grounded on the frame, circuit breakers supported below the frame, said circuit breakers connecting the line bus conductors with the aforesaid laterally extending conductors, and a liquid dielectric filling the sheaths and junction boxes.
31. In combination, a longitudinally extending frame supported in overhead position, columns for supporting said frame, said frame being divided into bays, a longitudinally extending bus supported on the longitudinal frame along one side thereof, said bus comprising individual phase conductors sub-divided into sections extending between bays, a pair of said sections of each phase conductor being joined endwise in alinement, alternate pairs of sections being disposed on different levels, junction boxes enclosing the adjacent ends of bus conductor sections, three-way connections in said junction boxes for joining adjacent ends of bus conductor sections, line bus conductors including oil circuit breakers in series therewith extending transversely of the frame and joined to the three-way connections in the junction boxes, and individual metallic sheaths for the line bus conductors and for the main bus conductors connected to said junction boxes, said sheaths and junction boxes being grounded on the frame and filled with liquid dielectric.
32. In an article of manufacture for constructing a bus and switch station comprising a plurality of bays, a bus and circuit breaker unit comprising a frame, a plurality of pairs of detachable circuit breaker connectors mounted in insulated relation on said frame, each pair comprising a bus connector and a line connector, housings for said line connectors, and housings for said bus connectors, said line connector housings having outlets, junction boxes connected to said outlets and line conductor sheaths joined to said junction boxes and disposed in a substantially common plane, sectional bus conductors extending longitudinally of the frame and having sheaths, junction boxes in the sheaths of certain ones of said bus conductors providing connection from the bus conductors to the bus connectors, and couplings for the bus conductor sections between bays.
33. In a bus and switch station, a plurality of bays comprising individual frame members, circuit breakers supported on said individual frame members, transverse line bus conductors connected to said circuit breakers and mounted on said individual frame members, sectional bus conductors individual to the bay connected to said circuit breakers and mounted on said frame, and couplings for the sectional bus conductors for joining adjacent bays.
34. In a bus and switch station, a plurality of bays comprising individual frame members, circuit breakers supported on said individual frame members, transverse line bus conductors connected to said circuit breakers and mounted on said individual frame members, sectional bus conductors individual to the bay connected to said circuit breakers and mounted on said frame, and couplings for the sectional bus conductors

- for joining adjacent bays, said couplings comprising expansion joints disposed between bays.
35. In a bus and switch station, bays having unit frames, circuit breakers mounted on said unit frames and connected to the main bus, line conductors mounted on said frame and connectible through said circuit breakers, and joints between bus conductors of adjacent bays comprising short conductors connectible between the bus conductors of adjacent bays. 5
36. In a bus and switch station, bays having unit frames, circuit breakers mounted on said unit frames and connected to the main bus, line conductors mounted on said frame and connectible through said circuit breakers, joints between bus conductors of adjacent bays comprising short conductors connectible 10 between the bus conductors of adjacent bays, individual sheathing for the bus and line phase conductors, and junction boxes on the sheathing at each end of each bay. 15
37. In a bus and switch station, bays having unit frames, circuit breakers mounted on said unit frames and connected to the main bus, line conductors mounted on said unit frames and connectible through said circuit breakers, joints between bus conductors of adjacent bays comprising short conductors connectible 20 between the bus conductors of adjacent bays, tubular sheaths for enclosing said bus conductors, junction boxes for connecting said sheaths, and expansion joints in 25 the sheaths connected between said junction boxes. 30
38. As a new article of manufacture, a bus and switching station for high tension multiphase alternating current comprising an elevated frame of structural steel, a high tension network of main bus and line busses supported thereupon, enclosed circuit breakers suspended from the framework for connecting or disconnecting at will the main bus and line busses, reactors individual to the phase conductors of a line mounted at the foot of the elevated frame, the network on the frame including the switches having the power conductors thereof individually sheathed and insulated throughout their length by grounded metallic sheaths containing liquid insulation, single phase underground cables extending from the reactors upwardly along a side of the frame to the top thereof, and junction boxes mounted along an edge of the frame for joining the said single phase cables to the line bus conductors on the frame. 45
39. A bus and switch station comprising a structural frame supported in elevated position, said frame being divided into bays, a longitudinally extending main bus common to the bays, said bus comprising phase conductors, transversely extending line busses comprising phase conductors, each line bus 50 being individual to a bay, circuit breakers suspended from the frame adjacent the overpass of the line bus and main bus and adapted to connect the line bus and main bus, junction boxes housing the connections of the circuit breakers and the line bus and main bus, individual sheathing covering the phase conductors of the main bus and line bus and joining said junction boxes, said sheathing and junction boxes containing a liquid dielectric, reactors, a line having conductors connected individually in series with the reactors, and single phase cables extending underground from said reactors to the overhead frame along the side of the frame, and junction boxes in which the cable conductors and line bus conductors are joined. 55
40. In a bus and switching station a plurality of units each comprising a unit frame, longitudinally extending bus conductors and transversely extending line conductors, pairs of disconnecting terminals for the bus conductors and the line conductors adapted to cooperate with circuit breakers having disconnecting terminals, grounded metallic sheathing joined to the unit frame and enclosing individually the conductors and terminals of each phase, insulating means within the sheaths for holding the conductors in relatively fixed position within said sheaths, means for supplying liquid insulation for each of the sheaths, and couplings at the ends of the bus conductors for facilitating the attachment of the bus conductors of adjacent units. 60
41. In a bus and switch station for multiphase alternating current, a plurality of units comprising each a unit frame, longitudinally extending bus conductors and transversely extending line conductors, pairs of disconnecting terminals for the bus conductors and the line conductors, said terminals being adapted to cooperate with circuit breakers having disconnecting terminals, grounded metallic sheathing joined to the unit frame and enclosing individually the conductors and terminals of each phase, insulating means within the sheaths for holding the conductors in relatively fixed position within said sheaths, means for supplying liquid insulation for each of the sheaths, couplings at the ends of the bus conductors for facilitating the attachment of the bus conductors of adjacent units, and expansion joints in the sheaths of the bus conductors for each unit. 65
42. In a bus and switch station for multiphase alternating current, a plurality of units comprising each a unit frame, longitudinally extending bus conductors and transversely extending line conductors, circuit breakers for connecting the bus and line conductors of each unit, grounded metallic sheathing joined to the frame and enclosing individually the conductors of each phase, insulating means within the sheaths for hold- 70 75 80 85 90 95 100 105 110 115 120 125 130

- ing the conductors in relatively fixed position within said sheaths, liquid supply and expansion tanks individual to and mounted on each unit frame for supplying liquid insulation for each of the sheaths, couplings at the ends of the bus conductors for facilitating the connection of the bus conductors of adjacent units, and expansion joints in the sheaths of the bus conductors for each unit. 5
43. In a bus and switch station for multi-phase alternating current, a unit construction comprising a rigid unit frame, longitudinally extending bus conductors and transversely extending line conductors, disconnecting terminals for the bus conductors and the line conductors adapted to cooperate with terminals of oil circuit breakers, grounded metallic sheathing joined to the frame and enclosing individually the conductors and terminals of each phase, insulating means within the sheaths for holding the conductors in relatively fixed position within said sheaths, means for supplying liquid insulation for each of the sheaths, quick detachable couplings at the ends of the bus conductors, and junction boxes at the ends of the sheaths of the bus conductors for enclosing said quick detachable couplings. 10
44. In a system of construction for bus and switch stations, a unit comprising a rigid metallic frame member, longitudinally extending bus conductors and transversely extending line conductors, disconnecting terminals for the bus conductors and the line conductors adapted to cooperate with circuit breaker terminals, grounded metallic sheathing joined to the rigid frame and enclosing individually the conductors and terminals of each phase, insulating means within the sheaths for supporting the structures in relatively fixed position therein, connections for supplying liquid insulation for each of the sheaths, couplings at the ends of the bus conductors for facilitating the connection of the bus conductors of one unit to an adjacent unit, junction boxes having removable walls to provide access to said couplings, and expansion joints in the sheaths between adjacent units. 15
45. Oil immersed electric switch gear comprising casings, means for rigidly supporting said casings, conductors such as bus bars extending into the casings, metal tubes enclosing the conductors intermediate of said casings; connections for joining the tubes and casings including sockets in telescopic engagement with the tubes, and oil tight sleeves between the tubes and sockets. 20
46. Oil immersed electric switch gear comprising a structural framework, casings thereon, conductors disposed between said casings and extending into the casings, metal tubes enclosing the conductors intermediate of said casings, connections including sock- 25
- ets in telescopic engagement with the tubes for joining the tubes and casings, said sockets having flanged ends for connection to the casings, and oil tight sleeves between the tubes and sockets. 70
47. Oil immersed electric switch gear comprising a supporting structure, casings thereon, conductors disposed between said casings and extending into the casings, metal tubes disposed intermediate of said casings for enclosing the conductors, insulators in the tubes for centering the conductors therein, connections for joining the tubes and casings comprising sockets in telescopic engagement with the tubes and oil tight sleeves between the tubes and sockets. 75
48. Oil immersed electric switch gear comprising a supporting structure, casings disposed thereon, conductors disposed between said casings and extending into the casings, metal tubes disposed intermediate of said casings for enclosing the conductors, insulators in the tubes for centering the conductors therein, connections for joining the tubes and casings comprising sockets in engagement with the tubes, and oil tight sleeves between the tubes and sockets, said sockets having flanged ends adapted to be bolted to the walls of the casings. 80
49. Oil immersed electric switch gear comprising a structural supporting framework, casings mounted thereon, terminals in the casings, conductors disposed between the casings and extending into the casings, metal tubes disposed intermediate of said casings for enclosing the conductors, connections between the tubes and casings comprising sockets in telescopic engagement with the tubes, oil tight sleeves between the tubes and sockets, and flexible conductors between the ends of the conductors and the terminals in the casings. 85
50. Oil immersed electric switch gear comprising a structural supporting framework, casings mounted thereon, terminals in the casings, conductors disposed between said casings and extending into the casings, metal tubes disposed intermediate of said casings for enclosing the conductors, insulators in the tubes for centering the conductors therein, connections including sockets in telescopic engagement with the tubes for joining the tubes and casings, oil tight sleeves between the tubes and sockets, and flexible conductors for joining the aforesaid conductors to the terminals in the casings. 90
51. Oil immersed electric switch gear comprising supporting means, casings mounted thereon, terminals in the casings, conductors disposed between said casings and terminating in the casings, flexible electric connections between the ends of the conductors and the terminals, tubing extending between casings and covering said conductors, each 105

length of tubing between casings comprising an expansion joint.

52. Oil immersed electric switch gear comprising casings, conductor lengths extending between and terminating in said casings, means for supporting said casings coextensive with said conductors, flexible connections in the casings between conductor lengths, and lengths of tubing between adjacent casings, 10 each length of tubing comprising an oil tight expansion joint.

53. Oil immersed electric switch gear comprising casings, conductor lengths extending between and terminating in said casings, flexible connections in the casings between conductor lengths, and lengths of tubing between adjacent casings for enclosing said conductor lengths, each length of tubing comprising an oil tight expansion joint, and a steel frame- 15 20 work to which said casings are connected and upon which the aforesaid parts are supported.

54. In a system of the class described, the combination of a plurality of junction boxes, 25 short lengths of conductor extending from junction box to junction box, supporting means for mounting said junction boxes coextensive with said conductors, flexible connections in the junction boxes, between adjacent ends of the conductors, short lengths of thin walled tubing enclosing the conductors and being connected to the junction boxes to form fluid tight sheathing, said sheathing including expansion joints, said sheathing being filled with insulation which is fluid at all 30 35 operating temperatures, and an expansion tank for the fluid insulation connected to the sheathing.

55. In a station adapted for outdoor service, the combination of a plurality of junction boxes, short lengths of conductor extending from junction box to junction box, flexible connections in the junction boxes joining the adjacent ends of conductor lengths and 40 45 permitting expansion and contraction, short lengths of thin walled tubing including expansion joints enclosing the conductors and joined between adjacent junction boxes, said tubing and junction boxes being filled with insulating liquid which is fluid at all 50 55 operating temperatures, an expansion tank connected to one of the junction boxes, and a rigid steel supporting framework for mounting the junction boxes.

55. In a bus and switch station, a structural supporting framework, bus conductors disposed on said framework coextensive therewith, cross conductors disposed on said framework transversely thereto and below 60 said bus conductors, and line conductors terminating in said station substantially centrally of said framework.

57. A bus and switch station of the class described, comprising a structural supporting framework, bus conductors disposed on

said framework longitudinally coextensive therewith, cross conductors disposed on said framework below said bus conductors and transversely thereto, line conductors, means for terminating said line conductors in said station between the sides of said framework, and switching means depending from said framework for connecting said conductors. 70

58. A bus and switch station of the class described, comprising a supporting framework extending in a substantially horizontal plane, bus conductors disposed on said framework longitudinally coextensive therewith, cross conductors disposed on said framework in a plane below said bus conductors and extending transversely to said framework, line conductors terminating vertically, substantially centrally of said framework, and switching means for said conductors connected removably to said framework and depending therefrom. 75 80 85

59. In a bus and switch station having a supporting framework extending in a substantially horizontal plane, circuit breaker means removably mounted on said frame and perpendicularly depending therefrom, contacts for said circuit breaker means, junction boxes mounted on said framework adjacent said contacts and offset therefrom, bus conductors connected to said junction boxes, and connections extending from said contacts to said junction boxes. 90 95

60. In a bus and switch station comprising a structural framework extending in a substantially horizontal plane, bus conductors disposed on said framework longitudinally coextensive therewith, line conductors terminating in said station from the side of said frame, said line conductors being disposed on said framework above said bus conductors and extending transversally to said framework. 100 105

61. In a bus and switch station comprising a structural framework extending in a substantially horizontal plane, bus conductors disposed on said framework longitudinally coextensive therewith, line conductors terminating in said station from the side of said frame, said line conductors being disposed on said framework above said bus conductors and extending transversally to said framework, and switching means removably disposed on said framework and perpendicularly depending therefrom. 110 115

62. In a bus and switch station of the class described, comprising a structural framework extending overhead in a substantially horizontal plane, a bus comprising phase conductors disposed on said framework longitudinally coextensive therewith, a line comprising single phase cables entering the overhead framework along the side thereof, said cables extending transversally of said framework between said phase conductors, and junction boxes for joining the 120 125 130

cable conductors and the line bus conductors.

63. In a bus and switch station, a supporting framework, posts for mounting said framework in an overhead position extending in a substantially horizontal plane, busses disposed on both sides of said framework and extending longitudinally coextensive therewith, circuit breakers for said busses removably disposed on said framework and perpendicularly depending therefrom, junction boxes for said circuit breakers mounted on said framework, a line entering said overhead framework along one side thereof, said line branching on said framework to said junction boxes.

64. In a bus and switch station, a supporting framework, posts for mounting said framework in an overhead position extending in a substantially horizontal plane, busses disposed on both sides of said framework and extending longitudinally coextensive therewith, circuit breakers for said busses removably disposed on said framework and perpendicularly depending therefrom, junction boxes for said circuit breakers mounted on said framework, a line entering said overhead framework along one side thereof, a current transformer for said line mounted on said framework for receiving said entering line, a potential transformer mounted on said framework, said line branching from said current transformer to said potential transformer.

65. In a bus and switch station, a supporting framework disposed in an overhead position in a substantially horizontal plane, said framework being divided into bays, a main bus and a reserve bus, each bus comprising phase conductors and being disposed on said framework longitudinally coextensive therewith, circuit breakers for said busses removably disposed on said framework and perpendicularly depending therefrom, junction boxes on said framework above said circuit breakers, a line comprising single phase cables entering said overhead framework on one side thereof, current transformers mounted on said framework for receiving said cables, potential transformers mounted on said framework, said cables branching from said current transformers to said potential transformers.

66. In a bus and switch station having an elevated supporting framework extending in a horizontal plane, busses disposed on said framework on either side thereof and longitudinally coextensive therewith, junction boxes mounted on said framework, circuit breakers suspended from said framework below said junction boxes, a junction box mounted on said framework centrally thereof, a potential transformer depending from said framework below said centrally disposed junction box, a current transformer mounted on said framework, a line entering

said current transformer, said line extending to said junction boxes of said circuit breakers and to said centrally disposed junction box of said potential transformer, and connections from said junction boxes to said busses. 70

In witness whereof I hereunto subscribe my name this 1st day of March, 1928.

ALLEN M. ROSSMAN.
